ELECTRIC DOOR OPERATOR

William G. Heinsman, Chicago, Ill., and Jack M. Roehm and Herbert S. Wille, Niles, Mich., assignors to Kawneer Company, Niles, Mich., a corporation of Delaware

Filed Jan. 2, 1959, Ser. No. 784,673

49 Claims. (Cl. 268—33)

The present invention relates to electric door operators and, more particularly, to an improved single-acting operator for positively controlling the opening and closing movements of a door.

It is an object of the present invention to provide a new and improved electric door operator for automatically opening and closing a door and for positively controlling the movement of the door during its opening and closing.

It is another object of the present invention to provide an electric door operator which has excellent performance characteristics and is safe and dependable in operation.

It is yet another object of the present invention to provide an electric door operator for initially opening and closing a door at an optimum speed and for moving the door adjacent both its open and closed speed at a slower latching speed.

It is another object in accordance with the previous object to rapidly change the speed of the door from its optimum speed to its latching speed.

It is another object of the present invention to provide an electric door operator embodying a positional servomechanism for developing a door moving torque having an initially high value for overcoming the inertia of the door, an intermediate constant value for driving the door at an optimum speed throughout substantially the entire movement of the door, and a final value decreasing to zero to provide for a gradual reduction of the driving force of the motor.

It is still a further object of the present invention to provide an electric door operator disposed substantially within a transom element of a doorway frame.

It is another object of the present invention to locate the mechanical components of an electric door operator within a transom element of a doorway construction and the electrical circuit of the operator within the transom element and door jambs of the doorway construction.

It is a further object of the present invention to provide an electric door operator for automatically returning a door to its open or closed position incident to manual displacement of the door in either direction away from either its open or closed position.

It is still a further object of the present invention to provide an electric door operator which is adapted to be set to automatically open and close a door on a selected side of a doorway.

It is another object of the present invention to provide an electric door operator which positively controls the opening and closing movement of a door on one side of a door frame yet which permits panic or manual opening of the door on the other side of the door frame.

It is a further object of the present invention in accordance with the previous object to provide an operator which automatically returns the door to its closed position after panic or manual opening of the door and which thereafter is able to automatically open and close the door without manual attention.

It is another object of the present invention to provide an automatic door operator which is adapted to be conditioned to operate as a double-acting door closer.

It is another object of the present invention to provide an electric door operator which develops when the door is

2

in either its open or closed position a positive rotative torque for opposing in and out wind pressure.

It is a further object in accordance with the previous object to provide a rotative torque which is proportional to door displacement and reaches a maximum value before the door rail leaves the door jamb.

It is still a further object of the present invention to provide an electric door operator that immediately arrests the closing movement of the door when a person stands adjacent to the exit side of the doorway.

Other objects and advantages of the present invention will become apparent from the following description of illustrative embodiments thereof, in the course of which reference is had to the accompanying drawings, wherein:

15 FIG. 1 is a perspective view of a door and doorway construction provided with an electric door operator embodying the features of the present invention for automatically opening and closing the door;

20 FIG. 2 is a partially schematic, partially diagrammatic, oversimplified view illustrating certain features of the electric door operator of FIG. 1, and showing particularly the positional servomechanism;

FIG. 3 is a fragmentary top plan view of a follower device embodied in the electric door operator of FIG. 1;

25 FIG. 4 is a schematic circuit diagram of a potentiometer network embodied in the electric door operator of FIG. 1;

FIG. 5 is a schematic circuit diagram of a modification of the potentiometer network of FIG. 4;

30 FIG. 6 is a schematic circuit diagram of yet another modification of the potentiometer network of FIG. 4;

FIG. 7 is a schematic diagram of a damping subcircuit and a motor interrupting subcircuit embodied in the schematic circuit diagram of FIG. 2;

35 FIG. 8 is a detailed schematic circuit diagram of the electric door operator of FIG. 1;

FIG. 9 is a diagrammatic top plan view of the doorway construction and door of FIG. 1 illustrating various movements of the door relative to the doorway;

40 FIG. 10 is a diagram illustrating the magnitude of the voltage existing at various points in the potentiometer network of FIG. 4 and the relative magnitude of voltage applied to a control winding of a servomotor during automatic operation of the door operator of FIG. 1;

45 FIG. 11 is a diagram illustrating the magnitude of voltage applied to a damping winding of the servomotor during automatic operation of the operator;

FIG. 12 is a diagram of the magnitude of the slider voltage in the potentiometer network of FIG. 4;

50 FIG. 13 is a diagram illustrating the magnitude of voltage applied to the control winding of the servomotor when the operator is panic or manually operated;

FIG. 14 is a diagram illustrating the magnitude of voltage applied to the damping winding of the servomotor 55 when the operator is panicked or manually operated;

FIG. 15 is a diagram illustrating the magnitude of voltage applied to the control winding of the servomotor when the operator functions as a double-acting door closer;

FIG. 16 is a diagram illustrating the magnitude of voltage applied to the damping winding of the servomotor when the operator functions as a double-acting door closer;

60 FIG. 17 is a fragmentary elevational view of a component of the control circuit used to control the magnitude of the voltage applied to the control winding during panic operation of the door.

Briefly, the electric door operator embodying the principles of the present invention functions automatically to open and close a door on one side of a doorway in response 65 to movement of one way traffic through the doorway. It positively controls the speed of the door and provides a normal opening or closing speed throughout most of the

movement of the door and then a latching speed adjacent to the door open or closed position. The operator permits panic or manual opening of the door on the other side of the doorway and thereafter automatically returns the door to its closed position, the operator being able to automatically open and close the door without resetting or repairing any panic devices. The door may also be automatically held in its open position on one side of the doorway for an indefinite period of time. In addition, the operator is adapted to function as a double-acting door closer to automatically return the door to its closed position after the door has been manually opened on either side of the doorway. The electrical and mechanical components of the electric door operator are disposed within the doorway construction and are not visible on either side of the construction, whereby a modern appearing entrance is provided.

The operator comprises a positional servomechanism which is either holding a "null position" or seeking a "null position." The servomechanism is controlled by an electrical control system including a treadle mat subcircuit, a damping subcircuit and a motor interrupting subcircuit. An electric servomotor of the servomechanism is in driving engagement through a gear assembly with a door spindle mechanically connected to the door and includes a control winding energized by a potentiometer network. When a person actuates the treadle mat subcircuit, the potentiometer network is unbalanced to provide for the motor control winding a driving voltage which causes the door to move to its open position and the servomechanism to seek a door open "null position." The servomechanism further embodies a mechanical follower or feedback device for rebalancing the potentiometer network and controlling the magnitude of the driving voltage supplied to the motor control winding. Specifically, the network develops a driving voltage having an initially high magnitude to overcome the inertia of the door, a lower substantially constant magnitude to move the door at an optimum speed, and a magnitude decreasing to zero to provide for a gradual reduction in the driving force of the motor. After a person has passed through the doorway, the treadle mat circuit is deactuated to again unbalance the network to provide a driving voltage for the motor control winding thereby to cause the servomechanism to seek a door closed "null position."

The door during either its opening or closing movement first moves at a normal optimum speed but during its last 30 degrees of movement travels at a reduced latching speed. When the door begins to move into its last 30 degrees of travel, door position-sensitive switches are closed to operate the damping subcircuit throughout the 30 degrees of latching movement and simultaneously to operate the motor interrupting subcircuit for a few degrees of movement. The damping subcircuit effects the energization of a damping winding in the servomotor to develop a resistive force having a magnitude proportional to the speed of the motor. The motor interrupting subcircuit causes the motor control winding to be open cirkuted for a predetermined time interval to permit the motor to be abruptly halted under the exclusive control of the damping subcircuit.

With the servomechanism holding either its open or closed "null position," the motor damping winding is energized by the damping subcircuit to offer a resistive force to any sudden manual force, i.e., a force resulting from "in or out" wind gusts, children or the like tending to move the door away from its open or closed position. In the event the door is moved off its open or closed position, the network is unbalanced and the servomechanism immediately seeks its "null position." Thus, even though forces temporarily displace the door when in its open or closed position, the door is promptly and automatically returned to its former position. Moreover, within a limited angle about the null position, the restoring torque is proportional to the displacement of the door.

The operator is adapted to be set to automatically open

and close the door on a selected side of the doorway by adjustment of the control circuit. Although the door is automatically opened and closed on one side of the doorway, it may be panic operated on the other side of the doorway without rendering the door operator ineffective. After panic or manual movement, the door is returned to its closed position under the control of the potentiometer network which is unbalanced by the panic movement of the door. Hence, after manual release of the door the servomechanism seeks its door closed "null position" and when the door reaches its closed position, the operator is able thereafter without readjustment or repair to automatically open and close the door. Furthermore, by proper adjustment of the treadle mat subcircuit the operator is conditioned to function as a double-acting door closer so that after the door has been manually opened on either side of the doorway thereby to unbalance the potentiometer network, the door is returned to its closed position under the control of the unbalanced network.

Referring now to the drawings, and in particular to FIG. 1, an entrance 20 is illustrated as including a doorway construction 22 provided in a wall 23. The doorway construction 22 is an integral unit and comprises a pair of jamb members 24 and 26 interconnected by a transom tube 28 and a transom window 30. An electric door operator 32 embodying the principles of the present invention is shown in dotted lines within the transom tube 28 and is drivingly connected to a door 34 through an upper pivot pin or door spindle 36 extending into the transom tube 28. The door 34 swings horizontally within the doorway construction 22, and more particularly, is pivotally supported adjacent to one of its vertical edges by the upper pivot pin 36 and a lower angulated pivot pin 38 connected to the lower end of the jamb 26. A treadle mat 42 is supported on the floor 40 and extends perpendicularly from the wall 23 in the direction of traffic through the doorway, the mat 42 having an entrance side 42a on the right side of the doorway 22 and an exit side 42b on the left side of the doorway.

The electric door operator 32 is selectively single-acting, i.e., it is adjusted to automatically open and close the door 34 on either side of the doorway 22 and, accordingly, the operator 32 operates only in response to the passage of one way traffic through the doorway. For example, as shown, the door 34 opens and closes on the left side of the doorway 22, as viewed in FIG. 1, and therefore the direction of traffic is from the right side to the left side of the doorway 22. Very briefly, the operator 32 comprises a positional servomechanism which either seeks or holds a door in its open or closed position under the control of an electrical control circuit. Accordingly, the door 34 is at all times directly powered and controlled by the operator 32.

As best shown in FIG. 2, the servomechanism includes an electrical servomotor 44 in driving engagement with the door 34 through a gear assembly 46 and the upper door pivot 36. A potentiometer circuit, indicated generally by the reference numeral 47, is unbalanced by a treadle mat subcircuit, indicated generally by the reference numeral 49 in response to actuation of the treadle mat 42, thereby to provide a driving voltage for energizing a control winding 48 of the motor 44 to either open or close the door 34. The network 47 is rebalanced by a follower or feedback device 50 in driving engagement with the upper door pivot 36, which follower device 50 controls the magnitude of the driving voltage in accordance with the position of the door and reduces the driving voltage to zero when the door reaches its desired position. The electrical control circuit further includes (FIG. 7) a damping subcircuit, indicated generally by the reference numeral 52, operable to energize a damping winding 56 of the motor 44 whenever the door 34 has moved 60° of its 90° open and closing movement. The energization of the damping winding 56 occurs during the last 30° of travel to ef-

fect a latching speed slower than the normal opening or closing speed of the door 34 and also when the door is in either its open or closed position thereby to provide a resistive force to oppose sudden displacements of the door resulting from wind gusts, children, animals and the like. Simultaneously with the operation of the damping subcircuit 52, a motor interrupting subcircuit 54 (FIG. 7) is operated to temporarily deenergize the control winding 48 of the servomotor 44 to assure that the motor promptly slows down to the latching speed.

SERVOMOTOR

Considering now the electric door operator in greater detail, the motor 44, shown diagrammatically in FIGS. 2 and 8, is a conventional two-phase, squirrel-cage induction motor and as is well-known, has particular application where controlled power is essential. It is characterized by its ability to deliver nearly constant torque in either direction of rotation at speeds ranging from zero to over twelve hundred revolutions per minute and is capable of changing direction almost instantaneously.

The rotor of the squirrel-cage motor 44 has no windings and rotates in response to a rotating magnetic field produced by two separate field windings, i.e., the control winding 48 and a reference winding 60, the winding 60 being continually energized from an A.C. source 63. The windings are supplied with alternating voltages differing in phase by substantially ninety electrical degrees and to this end a condenser 62 is serially connected in the circuit for energizing the reference winding 60. The direction of rotation of the motor depends on the angular direction of rotation of the magnetic field, while the field rotation depends upon the phase relationship of the voltages across the control winding 48 and the reference winding 60. Thus, if the voltage across the control winding 48 leads the voltage across the reference winding 60, the motor 44 will rotate in a first direction while if the voltage across the control winding 48 lags the voltage across the reference winding, the motor 44 will turn in an opposite direction. Whenever the electric operator 32 is turned on, an A.C. voltage having a constant magnitude is impressed across the reference winding 60. However, in normal operation, the control winding is energized with an A.C. voltage only when the mat subcircuit 49 effects an unbalance in the network 47. In fact, it is the network 47 which controls both the magnitude of the driving voltage in the control winding 48 and the relative phase relation between the voltages in the control and reference windings 48 and 60, thereby to control the magnitude of motor torque and direction of motor rotation to obtain the desired door movement.

The servomotor 44 further includes a damping winding 56 which is energized by a constant voltage D.C. power circuit 58 under the control of the damping subcircuit 52, thereby to produce a stationary magnetic field within the space occupied by the rotor. The stationary magnetic field induces currents within the rotating rotor, with the result that an opposing magnetic field is developed to retard or resist the normal rotation of the rotor. Since the magnitude of the current induced within the rotor is proportional to the speed of the rotor, the resistance offered by the opposing magnetic field is directly proportional to the speed with which the rotor turns. Accordingly, when the rotor is turning at a normal rotary speed, a particular amount of resistance to rotation is offered, while as the rotor decreases in speed, progressively less resistance is offered to rotation of the rotor. Furthermore, when the rotor is stopped, no opposing resistance exists since no field currents are induced in the stationary rotor and no opposing magnetic field is produced.

GEAR ASSEMBLY

The door driving force is transmitted from the motor 44 to the upper door pivot 36 through the gear assembly 46. Specifically, the driving connection, as shown in FIG. 2, extends from a worm gear 64 mounted on the output shaft 44a of the motor 44 through a helical gear 66 secured to a vertical shaft 70 rotatably supported from the transom tube 28, through a drive pinion 68 secured to the shaft 70, to an intermediate gear 72 secured to a second vertical shaft 76 rotatably supported from the transom tube 28, and an intermediate pinion 74 secured to the shaft 76, and then to a bull gear 78 fixedly secured to the upper door pivot pin 36. As shown, the gear assembly 46 is of simple design and, since it is required to handle a relatively large amount of torque or power, the gears in the assembly 46, with the exception of the helical gear, are made from hardened steel while the shafts 70 and 76 and the lower door pivot 32 are also hardened.

POTENTIOMETER NETWORK

The potentiometer network 47 illustrated diagrammatically in FIG. 2 and in detail in FIG. 4, comprises a self-balancing A.C. type bridge network which supplies a driving voltage to the motor control winding 48 for effecting the opening or closing of the door 34 in response to actuation of the treadle mat subcircuit 49 by a person walking through the doorway 22. In FIG. 2 certain of the transformer windings and circuit connections shown in FIG. 4 have been omitted for the sake of simplicity but similar reference numerals refer to similar parts. Referring particularly to FIG. 4, the bridge network has a first branch comprising a secondary winding 92 of a step-up reference transformer 90 having its primary winding 91 connected across the A.C. voltage source 63 and has a second branch comprising a variable autotransformer 94, for example, a Variac, connected in parallel with the winding 92.

The A.C. bridge network further includes a center arm 96 having its first end 96a connected to a switch 97 which is operated by and forms a part of a control relay 160 and which is adapted to be moved under the control of the treadle mat subcircuit 49 (FIG. 2) to one of two different voltage levels on the winding 92. The second end 96b of the center arm 96 is connected to a slider 99 movable along the winding 94 to different voltage levels. A primary winding 98 of a suitable step-up transformer is serially connected in the arm 96 while the secondary winding 95 of the step-up transformer is serially connected in circuit with the motor control winding 48. When the servomechanism is holding an open or closed "null position," the ends 96a and 96b of the center arm 96 are connected to the same voltage levels; however, when the treadle subcircuit causes an unbalance in the network 47 and the servomechanism is seeking an open or closed "null position" the ends 96a and 96b of the center arm 96 are located at different voltage levels, thereby to provide a resultant driving voltage for the motor control winding 48.

More specifically, the approximate 115 volts of the A.C. voltage source 63 is stepped up to 140 volts by the reference transformer 90 so that the 140 volts appear across the first branch 92 of the A.C. bridge network 47 as well as the second branch 94. Accordingly, equal voltages exist at identical points or levels on the windings 92 and 94. When the servomechanism is in its door closed "null position" and the door is closed, the end 96a of the center arm 96 is connected through the switch 97 to a voltage level 100 on the winding 92 while the end 96b of the center arm 96 is connected through the slider 99 to a voltage level 102 on the winding 94. The voltage levels 100 and 102 are equal so that no voltage difference exists between the ends of the arm 96, whereby no current flows through the center arm and no voltage is

developed in the motor control winding 48. However, when the treadle mat subcircuit is actuated, the switch 97 is moved from the voltage level 100 to a voltage level 104 on the winding 92. Since the slider initially remains at the voltage level 102, a voltage difference exists across the arm 96 to produce in the motor control winding 48 a driving voltage having a phase leading the voltage in the reference winding 60 by substantially 90 electrical degrees. The servomechanism thus seeks a door open "null position" and opens the door 34. During the opening movement of the door the follower device 50 (FIG. 2) moves the slider 99 along the winding 94 to control the magnitude of the driving voltage, as described below, until the door reaches its open position wherein the slider 99 is moved to a voltage level 106 on the winding 92 which is equal to the voltage level 104 on the winding 92. No voltage difference exists across the arm 96 and no current flows through the center arm 96 with the result that the motor 44 is deenergized. Thus, the bridge network 47 is rebalanced and the servomechanism holds its door open "null position." In an electric door operator built according to the present invention, the servomechanism is designed to be slightly "underdamped" with the result that the servomechanism slightly overshoots the door open "null position." Specifically, the slider 99 slightly overshoots the voltage level 106 to produce in the control winding 48 a driving voltage having a phase lagging the voltage in the reference winding 60 by substantially 90 electrical degrees, thereby causing the slider 99 to return to voltage level 106.

In response to deactuation of the treadle mat subcircuit, the network 47 is again unbalanced and the switch 97 is returned to the voltage level 100 on the winding 92 thereby to provide across the center arm 96 a voltage differential. This voltage differential develops across the motor control winding 48 a driving voltage having a phase lagging the voltage in the reference winding 60 by 90 electrical degrees, thereby to cause the motor 44 to rotate in a direction opposite to that described above to close the door. The servomechanism now seeks its door closed "null position." During the closing movement of the door, the slider 99 is moved along the winding 94 under the control of the follower device 50 back to the voltage level 102 on the winding 94, which voltage level 102 is equal to the voltage level 100 so that no current flows through the center arm 96 and the motor control winding 48 is deenergized. It will be appreciated that as the servomechanism seeks either its door open or door closed "null position," the magnitude of the driving voltage applied to the motor control winding 48 is dependent upon the relative position of the switch 97 and the slider 99. However, when the servomechanism holds either its door open or closed "null position," the magnitude of the driving voltage is zero and the switch 97 and the slider 99 are at the same voltage levels.

FOLLOWER DEVICE

The follower device 50 illustrated diagrammatically in FIG. 2 feeds back to the A.C. bridge network 47 information regarding the position of the door 34 and thus effects the balance of the network 47. When the operator is functioning to automatically open and close the door 34, the follower device 50 rebalances the network 47 unbalanced by the mat subcircuit 49 and, accordingly, reduces the magnitude of the driving voltage in the motor control winding 48, while, when the operator functions as a door closer or is panic operated, the follower device 50 actually unbalances the network 47 to produce a driving voltage for the motor control winding 48 and thereafter rebalances the network to reduce the magnitude of the driving voltage. Assuming the operator 32 is set for automatic operation, the follower device 50 during movement of the door 34 moves the slider 99 along the winding 94 and provides a driving voltage having an initially high magnitude for overcoming the inertia of the structure and

quickly moving the door, a lower constant magnitude for moving the door at an optimum speed, and finally a magnitude decreasing to zero for limiting overshooting or hunting of the door. To this end, a cam and rack arrangement are connected between the A.C. bridge network 47 and the gear assembly 46 which has its shaft 76 in driving engagement with the door 34 through the gear 74, gear 78 and the door pivot 36. A cam 110 is fixedly secured to the upper end 76a of the shaft 76 and comprises a disk provided on its upper surface with a continuous camming groove 112, as best shown in FIG. 3. A follower roller or pin 114 of an elongated bar 116 continuously engages the groove 112 and effects reciprocal movement of the bar 116 incident to rotation of the cam 110, the bar 116 being supported from a roller bearing structure mounted on the transom tube 28. The right end of the follower bar 116 as viewed in FIG. 2 is provided with a plurality of rack teeth 118 which engage a pinion 120 supported at the upper end of a shaft 122 on which the slider 99 is mounted. The slider 99 is thus rotated by an amount proportional to the displacement or movement of the follower bar 116 which, in turn, is controlled by rotation of the cam 110 in response to door movement.

Considering now in greater detail the cam 110 and in particular the configuration of the continuous camming groove 112, attention is directed to FIG. 3. The continuous groove 112, defined in the upper surface of the cam 110, has a substantially constant width slightly greater than the diameter of the pin 114 so that the pin 114 freely rides in the groove but does not rattle or appreciably move transversely of the groove 112. It comprises an automatic groove section 132, 133, 134 intermediate an outer panic groove section 130, 131 and an inner panic groove section 135, 136. The automatic groove section comprises a straight groove portion 132, an arcuate groove portion 133, and a straight groove portion 134; the outer panic groove section comprises a straight groove portion 131 and an arcuate groove portion 130; and the inner panic groove section comprises a straight groove portion 135 and an arcuate groove portion 136.

If the closer 32 is set to open the door on the left side of the doorway 22, the cam 110 is in such a position that the follower pin 114 is located in the outer end of the straight groove portion 132, in the position shown in dotted lines and identified as 137. With the follower pin 114 in this position, the rack 116 causes the slider 99 to be located at the voltage level 102. FIG. 12 shows a diagram of the magnitude of the voltage of the end 96b and the slider 99 as it is moved under the control of the cam 110 during a conventional automatic opening and closing of the door 34. During the first 2½ degrees of door opening movement, the cam 110 rotates in a counterclockwise direction and the follower pin moves along the portion 132 thereby to displace the bar 116 and move the slider 99 from the voltage level 102 to voltage level 105. During the movement of the door from its 2½ degree open position to its 87½ degree open position, the cam 110 rotates and the follower pin 114 travels in the arcuate groove portion 133 (as shown) with the result that the bar 116 is not moved and the slider 99 remains at the voltage level 105. During the last 2½ degrees opening movement, i.e., 87½ degrees to 90 degrees, the cam 110 rotates so that the follower pin 114 travels along the groove portion 134 thereby to displace the follower bar 116 and move the slider 99 from the voltage level 105 to the voltage level 106. The pin 114 is now at the inner end of the groove portion 134 as shown in dotted lines and identified by reference numeral 138. As long as the door remains open, the slider 99 remains at the voltage level 106. During closing of the door, the cam rotates in a clockwise direction and the follower pin moves from the point 138 through the groove portions 134, 133, 132 back to the point 137 thereby to move the slider from the voltage level 106 back to

the voltage level 102, as shown by the arrows pointing to the left in FIG. 12.

The magnitude of the driving voltage applied to the motor control winding 48, the magnitude of the voltage at the first end 96a of the arm 96 (i.e., the switch voltage 97) and the magnitude of the voltage at the second end 96b of the arm 96 (i.e., the slider voltage 99) is illustrated in FIG. 10 for automatic opening and closing of the door on the left side of the doorway 26. The opening and closing movements of the door are also illustrated in FIG. 9 and are identified by reference letters A and B, respectively. In FIG. 10, the slider voltage is indicated by reference numeral 99 and is shown in full lines, the voltage at the switch 97 is identified by the numeral 97 and is shown in crossed lines, and the driving voltage which is proportional to the difference between the switch and slider voltages is illustrated by arrowed lines 48a drawn vertically between the switch and slider voltages. When the door is in its closed position and the servomechanism holds its door closed "null position," the switch voltage and the slider voltage are at equal voltage levels 100 and 102, respectively. However, when the switch 97 is moved from the voltage level 100 to the voltage level 104 under the control of the treadle mat subcircuit, the network 47 is unbalanced to apply an initially high driving voltage to the motor control winding 48 with the result that a high torque is developed to overcome the inertia of the door structure and quickly open the door. As the door opens, the follower pin 114 moves inwardly along the groove portion 132 to move the follower bar 116, thereby linearly to increase the slider voltage 99 and linearly decrease the voltage difference between the switch and the slider voltages. After 2½ degrees of door opening movement the follower pin 114 reaches the groove portion 133 and the slider 99 reaches the voltage level 105 with the result that the driving voltage reaches an intermediate value. The slider voltage remains at the voltage level 105 and the driving voltage remains at its intermediate value until the cam has rotated substantially one revolution and the door is in an 87½ degree open position. As the pin 114 moves in the groove portion 134 to again displace the bar 116, the slider voltage linearly increases while the driving voltage linearly decreases. When the follower pin 114 reaches the point 138, the slider 99 is at the voltage level 106 and the switch 97 is at voltage level 104. Thus, since voltage levels 104 and 106 are equal, the voltage at the ends 96a are equal with the result that no voltage difference exists across the center arm 96. Accordingly, the network 47 is rebalanced and no driving voltage is developed for the motor control winding 48.

The servomechanism holds its door open "null position" under the control of the treadle mat subcircuit and holds the door open as long as the mat subcircuit is not disturbed. If for any reason a force is applied to the door to move it either toward its closed position or toward a further open position, the cam 110 rotates and the follower pin 114 moves along the groove portions 134—135, thereby moving the slider 99 from the voltage level 106 toward either of the voltage levels 105 or 107 (FIG. 12). Accordingly, the follower device 50, instead of the treadle mat subcircuit, unbalances the bridge network 47 and the motor control winding is energized with a driving voltage having the necessary phase to return the door to its open position and the slider 99 to the door open "null position" 106. It should be observed that as the door moves farther from its open position, within a 2½ degree range in either direction, the magnitude of the driving voltage progressively increases to produce a progressively greater torque for returning the door to its open position. As described above, when the door is returned to its open position the network 47 is rebalanced and the driving voltage is reduced to zero.

The door is closed under the control of the treadle mat subcircuit by the switch 97 being moved from the voltage

level 104 to the voltage level 100, thereby to unbalance the network 47 and cause the servomechanism to seek its door closed "null position." The unbalanced network 47 develops a driving voltage which is so phase related to the voltage in the reference winding 60 to cause the motor to rotate in a direction opposite to that above, thereby to return the door to its closed position. As shown, the magnitude of the driving voltage during closing of the door is identical to the magnitude of the driving voltage during opening of the door and initially has a high value, a substantially constant intermediate value, and a value which decreases to zero. The follower pin moves from the point 138 to the point 137 along the groove portions 134, 133, 132 in exactly the reverse manner as described above. The slider 99, of course, moves from the voltage level 104 to the voltage level 105 between the 90 degree and 87½ degree open positions, remains at the voltage level between the 87½ degree to 2½ degree open positions, and moves from the voltage level 105 to the voltage level 102 between the 2½ degree open position to the closed position. When the follower pin 114 reaches the point 137, the slider voltage 99 is at voltage level 102 and the switch voltage 97 is at voltage level 100 with the result that the network 47 is rebalanced and the magnitude of the driving voltage is reduced to zero. The servomechanism now holds the door closed "null position" and retains the door in its closed position even though no driving voltage is supplied to the motor control winding 48. Thus, when drafts, wind currents, or the like tend to move the door away from its door closed position, it is the follower device 50 which unbalances the network 47. Specifically, the cam 110 rotates and the follower pin 114 moves along the groove portion 131—132 thereby to move the slider 99 toward either the voltage level 101 or 105 to unbalance the network 47 and produce for the motor control winding a driving voltage having a proper phase relative to the reference winding 60 to return the door to its closed position.

If the door operator is set to open and close on the right side of the doorway 22 (i.e., to effect opening movement C and closing movement D as shown in FIG. 9), then the cam 110 is moved as described hereinafter so that the follower pin 114 is located at the point 138 when the door 34 is in its closed position. In the same manner as described above, the follower pin travels from the point 138 through the groove portions 134, 133 and 132 to the point 137 and then back to the point 138 while the slider 99 moves from voltage level 106 to voltage levels 105 and 102 and back to voltage level 106 during automatic opening and closing of the door.

Furthermore, when the operator 32 is set to automatically open and close the door 34 on the left side of the doorway 26 and the door is panic opened on the right side of the doorway 22, the follower device 50 unbalances the network 47 and develops a driving voltage for automatically returning the door to its closed position. The cam 110 rotates clockwise to cause the follower pin 114 to move from the point 137 into the groove portions 131 and 130, the follower pin 114 reaching the groove portion 130 and the slider 99 moving from the voltage level 102 to the voltage level 101 after 2½ degrees of opening movement. Beyond the 2½ degree open position, the pin 114 remains in the groove portion 130 while the slider 99 remains at the voltage level 101. Incident to manual release of the door, the unbalanced network 47 causes the door to be automatically closed, whereby the pin 114 returns along the groove portions 130 and 131 to the point 137 while the slider 99 returns to the voltage level 100. When the operator is set to open the door 34 on the right side of the doorway 22 and the door is panic opened to the left side of the doorway 22, the follower device 50 unbalances the network 47 and develops a driving voltage for automatically returning the door to its closed position. The cam 110 rotates counterclockwise to cause the follower pin to travel from the point 138 into the groove portions 135 and

136 and the slider 99 to move from the voltage level 106 to the voltage level 107 within 2½ degrees of door opening movement.

In the event the operator is set to open on the left side of the doorway and is conditioned to act as a double-acting door closer, incident to manual opening of the door on the left side of the doorway, the follower device 50 unbalances the network 47 and produces a driving voltage. The cam 110 rotates counterclockwise and the follower pin 114 moves from the point 137 into the groove portions 132 and 133 with the result that the slider moves from the voltage level 102 to voltage level 105 within 2½ degrees of opening movement. Between the 2½ degree and 87½ degree open positions, the pin 114 remains in the groove portion 133 while the slider 99 remains at the voltage level 105 and between the 87½ degree and 90 degree open positions, the pin 114 moves along the groove portion 134 thereby to cause the slider 99 to move from the voltage level 105 to the voltage level 106. When the door is manually released, the unbalanced network 47 automatically causes the door to return to its closed position, whereby the pin 114 returns to its point 137 and the slider 99 returns to its voltage level 102. As the door is opened to the right side of the doorway, the cam rotates clockwise and the follower pin 114 moves from the point 137 into the groove portions 131 and 130 thereby to move the slider 99 from the voltage level 102 to the voltage level 101. During automatic closing of the door, the pin returns to its point 137 and the slider 99 returns to its voltage level 102. In the event the operator is set to open on the right side of the doorway 22 and is conditioned to act as a double-acting door closer, then incident to manual opening of the door on the left side of the doorway, the cam 110 rotates counterclockwise and the follower pin 114 moves from the point 138 into the grooves 135, 136 while the slider moves from voltage level 106 to voltage level 107. Incident to manual opening of the door on the right side of the doorway, the cam 110 rotates clockwise and the follower pin 114 moves from the point 138 into the grooves 134, 133 and 132 while the slider moves from voltage level 106 to voltage levels 105 and 102.

CONTROL CIRCUIT

Considering now the control circuit and referring particularly to FIG. 8, the circuit includes a pair of power conductors 237 and 239 which are connected to the A.C. voltage source 63, which, for example, may comprise 60 cycle electrical power supplied to buildings, dwellings and the like. The power for operating the electric door operator 32 is supplied by these conductors and is controlled by an on-off switch 139 which is serially connected in the power line 239 and is mounted, as shown in FIG. 1, to the jamb 24 to be readily accessible to manual actuation. A fuse 141 is also serially connected in the power line 239 while a motor fan 142 is connected across the lines 237 and 239 to provide continued air circulation in the transom tube by drawing air through a vent 40a into the tube and forcing air out of the tube through a vent 40b.

The power conductor 237 is grounded and is connected to one end of the primary winding 91 of the reference autotransformer 90 while the conductor 239 is connected to an intermediate point on the autotransformer winding 91, thereby to provide a voltage of 140 volts across the entire primary 91. This winding 91 causes an A.C. voltage to be developed across both the secondary winding 92 and the Variac winding 94 comprising the two branches of the Waxwell bridge network 47 and further supplies the power for the D.C. power supply circuit 58. A portion of the secondary winding turns, identified as 143, is used as a low voltage A.C. source, i.e., 12 volts, and supplies power to certain ones of the relays in the treadle mat subcircuit 49.

In order to energize the damping winding 56 during a damping operation with a D.C. current, the electric door

operator employs its own D.C. power supply circuit 58. Specifically, the circuit 58 is of the conventional rectifier type and is connected in parallel with the primary winding 91 of the transformer 90. The stepped up 140 volts appearing across the circuit 58 is rectified by a pair of serially connected silicon rectifiers 123 and 124, which rectifiers are further serially connected with a resistor 126 and a capacitor 128, one plate of which is connected to the grounded conductor 237. The capacitor is employed to filter the ripple voltage obtained from the rectifiers and to provide a substantially constant D.C. voltage of approximately 175 volts. The resistor 126 functions as a current limiting device to prevent the first instantaneous charge current from overheating the rectifiers 123 and 124. A resistor 130 is connected in parallel across the condenser 128 to provide a discharge path for the charge on the condenser when the power to the electric door operator 32 is turned off by the switch 139. As shown, the 175 volts is available at the junction of the capacitor 128 and the rectifier 124 which junction is hereafter identified as the positive terminal 144 of the D.C. power supply circuit 58. As described in greater detail hereinafter, the 175 volts of the D.C. power supply circuit 58 is used to energize the damping winding 56 of the motor 44 and to energize a relay in the treadle mat subcircuit.

1. Treadle Mat Subcircuit

Considering now the treadle mat subcircuit and referring specifically to FIGS. 2 and 8, the circuit comprises the treadle mat 42 which embodies an entrance foot-operated switch 80 having a pair of normally open contacts 81 and an exit foot-operated switch 82 also having a pair of normally opened contacts 83. When a person steps on the mat entrance side 42a and closes the switch contacts 81, an operate relay 140 is energized to close a pair of its contacts which complete a circuit for energizing a control relay 160. The control relay 160 operates to unbalance the Maxwell bridge network 47 by moving the switch 97 from the voltage level 100 to the voltage level 104 with the result that the servomechanism is caused to seek a door open "null position." As the person walks from the mat entrance side 42a to the mat exit side 42b, the entrance contacts 81 are opened and the exit contacts 83 are almost simultaneously closed, whereby a safety relay 150 is operated to close a pair of contacts which completes another circuit (shown only in FIG. 8) for energizing the control relay 160, which latter circuit is independent of the operate relay 140 so that the control relay 160 remains energized even though the entrance contacts open to deenergize the operate relay 140. As shown in the greatly simplified circuit of FIG. 2, the operate relay 140 and the safety relay 150 are interrelated so that the control relay 160 is energized through the operate relay 140 only when the safety relay 150 is unenergized. Accordingly, if someone stands on the mat exit side 42b, thereby to close the exit switch contacts 83 and operate the safety relay 150 to open the energizing circuit for the control relay 160, and thereafter a person steps on the mat entrance side 42a to energize the operate relay 140, the control relay 160 does not operate so that the network 47 remains balanced and the door remains in its closed position. Accordingly, an inattentive person standing within the range of opening movement of the door is not injured by the opening door since the door is rendered ineffective by the presence of the person on the mat exit side 42b.

Referring now more specifically to FIG. 8, in which the relays, switches and contacts are shown in the position they assume when the door is in its closed position, as a person walks through the entrance 20, he first steps on the entrance side 42a of the mat 42 and actuates the mat entrance switch 80 to close the switch contacts 81. The closure of the switch contacts 81 completes an energizing circuit for the operate relay 140 from ground, a conductor 145, switch contacts 81, a conductor 146, a

winding 140a of the operate relay 140, a conductor 147, the 12 volt A.C. power source 143, a conductor 148 and to ground. The operation of the relay 140 causes a single pair of contacts 149 to close, thereby to complete an energizing circuit for the control relay 160 as follows: the positive terminal 144, a conductor 151, a current limiting resistor 153, a conductor 155, the contacts 149, a conductor 157, contacts 154, conductor 159, the relay winding 160a of the control relay 160, a conductor 161, the power conductor 237, to ground. The energization of the control relay 160 causes the contact wiper 97a of the switch 97 to disengage a contact 100a and to engage a contact 104a, and further causes a pair of contacts 162 to open, a pair of contacts 164 to close, and a pair of contacts 166 to close. The closure of the contacts 97a-104a causes the end 96a of the arm 96 to be disconnected from the voltage level 100 and connected to the voltage level 104 through the following circuit: a conductor 163, a socket 165, a plug 167, and a conductor 168. As indicated above, the movement of the switch 97 unbalances the network 47 which produces a driving voltage for the motor control winding and effects the opening of the door. The closure of the contacts 164 disconnects a door position-sensitive switch 174 from and connects a door position-sensitive switch 170 to the damping winding 56 for a purpose described hereinafter. The closure of the contacts 166 completes a holding circuit for the control relay 160 so that the control relay remains energized independently of the safety relay 150. The conductor 159, the contacts 166 and a conductor 169 comprise part of the holding circuit and are in parallel with the contacts 154 so that even though the safety relay 150 is energized and its contacts 154 open, the control relay remains energized.

As a person passes from the mat entrance side 42a to the mat exit side 42b, the mat exit contacts 83 usually close a short time interval after the opening of the mat entrance contacts 81, with the result that for about a quarter of a second the operate relay 140 is deenergized thereby to open both the energizing and holding circuits for the control relay 160. This quarter of a second time interval generally occurs while the door is opening. In order to maintain the control relay 160 energized during this time interval, a condenser 173 is connected across the control relay winding 160a to be energized by current from the D.C. positive terminal 144 during closure of the mat entrance contacts 81. Hence, during the short time interval that the energizing circuit for the control relay 160 is open, the charge stored in the condenser 173 discharges through the control relay winding 160a thereby to maintain the control relay 160 energized during the quarter of a second time interval.

The person stepping on the mat exit side 42b causes the exit switch contacts 83 to close, thereby to complete an energizing circuit for the safety relay 150. Specifically, the circuit is from ground, a conductor 145, contacts 83, conductor 177, the relay winding 150a of the safety relay 150, a conductor 178, the 12 volt A.C. source 143, the conductor 239, and ground. The energization of the safety relay 150 effects the closure of contacts 152 and 158 and the opening of contacts 154 and 156. The closure of the contacts 152 completes a second energizing circuit for the control relay 160 from the positive terminal 144, the resistor 153, the conductor 155, a conductor 179, the contacts 152, the conductor 157, the conductor 169, the contacts 166, the winding 160a, the conductor 161, the conductor 237, and ground. Hence, the control relay 160 remains energized by the above described second energization circuit even though the operate relay 140 is deenergized and the first energization circuit for the control relay 160 is open circuited by the opening of the contacts 149 incident to the person stepping off the mat entrance side 42a.

The opening of the contacts 156 open circuits the connection between the contact 100a and the voltage level

100 on the winding 92 but performs no useful function at this time, inasmuch as the left end 96a of the arm 96 is connected to the voltage level 104 through the switch 97 and contact 104a. The above connection, as shown, 5 comprises the contact 100a, a conductor 125, the contacts 156, a conductor 127, the socket 165, the plug 167, a conductor 129 and the voltage level 100. The closure of the contacts 158 causes the operation of the damping subcircuit with the attendant energization of the damping winding 56 in the event the door is closing, as described in greater detail below, but performs no useful function at this time because the contacts 162 are opened under the control of the control relay 160. The control relay 160 remains energized and the servomechanism 10 holds the door open "null position" with the switch 97 at voltage level 104 and the slider at voltage level 106 as long as the person remains on the mat exit side 42b and closes the mat exit contacts 83.

When the person steps off of the mat exit side 42b 20 thereby to open the contacts 83, the safety relay 150 is deenergized and its contacts 152 are opened thereby to open the second energizing circuit for the control relay 160. The deenergization of the control relay 160 does not occur immediately but is delayed approximately a quarter 25 of a second while the charge on the condenser 173 discharges through the relay winding 160a. The deenergization of the control relay 160 causes the wiper contact 97a to disengage the contact 104a and to engage the contact 100a, thereby to disconnect the end 96a of the arm 96 30 from the voltage level 104 and connect it to the voltage level 100. As described above, the network 47 is unbalanced and produces for the motor control winding 48 a driving voltage which causes the door to be moved to its closed position. Incident to deenergization of the safety 35 relay 140 and the control relay 160, the relays, switches, and contacts assume the positions shown in FIG. 8.

2. Damping Subcircuit

The damping subcircuit 52 is illustrated in FIGS. 7 and 40 8 and briefly functions to energize the damping winding 56 of the motor 44 during the last 30 degrees of door opening or closing movement, thereby to provide a door latching speed which is substantially slower than the normal opening and closing speed of the door. As illustrated 45 in FIG. 2, a pair of door position-sensitive switches 170 and 174 are both actuated by a cam 180 during the first 30 and last 30 degrees opening and closing movement 50 of the door and are selectively connected by the contacts 162, 164 under the control of the control relay 160 between the damping winding 56 and the D.C. terminal 144. The cam 180 moves in response to movement of the door 34 and is fixedly secured to the upper end of the door pivot 36 for cooperation with the door position-sensitive switches 170 and 174 supported on structure mounted on the 55 transom tube 28. The cam 180 is disc shaped and has a 60 degree peripheral cam portion 180a for selectively engaging the contact actuating levers 170a and 174a of the switches 170 and 174. When the door is in its closed position, the cam engaging portion of the lever 174a is in 60 engagement with the middle of the cam portion 180a so that irrespective of the direction of door movement the contacts 175 of the switch 174 are closed and the contacts 176 of the switch 174 are opened. In contrast, the cam engaging portion of the lever 170a is spaced 65 from the cam portion 180a to be engaged by the cam 180 to close contacts 171 and open contacts 172 only after the door has been moved to a 60 degree open position on the right side of the doorway 22.

When the control relay 160 is energized in response to a 70 person stepping on the mat entrance side 42a, the contacts 162 are opened thereby to open a first energization circuit described below for the damping winding and the contacts 164 are closed thereby conditioning a second circuit for energizing the damping winding 56. This circuit, referring 75 to FIG. 8, is as follows: the D.C. terminal 144, a conduc-

tor 181, a current limiting resistor 182, a conductor 183, open contacts 171, the socket 165, the plug 167, the conductor 184, the closed contacts 164, a conductor 185, an inductor 186, the damping winding 56, the power conductor 237 and ground. Although the contacts 175 are closed by the cam 180 when the door is in its closed position, the motor damping winding 56 is not energized through the switch 174 since the contacts 162 are opened. The damping winding 56 is also not energized through the switch 170 in the door closed position and throughout 5 60 degrees of door opening movement since the contacts 171 are opened. When the door reaches its 60 degree open position the switch contacts 172 are opened and the contacts 171 are closed with the result that the above described second energization circuit for the damping winding 56 is completed and current flows through the winding 56 to effect a damping of the motor as described above. Current flows through the damping winding 56 during 10 the movement of the door between its 60 degree and 90 degree open positions and also as long as the door remains in its door open position. Incident to deenergization of the control relay 160 by the treadle mat subcircuit 49, the contacts 164 are opened thereby to open the above described second energization circuit for the damping winding 56 and the contacts 162 are closed to condition the 15 first energization circuit for the damping winding 56 to operate as follows (FIG. 8): the D.C. terminal 144, the conductor 181, the resistor 182, the conductor 183, the open contacts 175, the socket 165, plug 167, a conductor 187, contacts 162, conductor 185, the inductor 186, damping winding 156, power conductor 237, and ground. Hence, the control relay 160 serially connects the switch 174 to the damping winding 56 and disconnects the switch 170 from the damping winding so that even though the contacts 171 remain closed the damping winding 56 becomes deenergized. When the door reaches its 30 degree open position, the cam portion 180a actuates the switch 174 with the result that the contacts 176 open and the contacts 175 close, thereby to complete the first energizing 20 circuit through contacts 162 for the damping winding 56. The damping winding 56 of the motor 44 is energized during the movement of the door 34 from its 30 degree open to its closed position and remains energized for as 25 long as the door is in its closed position.

It should be appreciated that the inductor 186 is serially connected with the damping winding to reduce the torque loss resulting from the interaction of the magnetic fields developed by the control and damping windings. In a commercial embodiment of the present invention, the control and damping windings are wound on the same slots of the stator with the result that the windings act like the primary and secondary of a transformer. Whenever the damping winding 56 is energized the capacitor 128 of the D.C. voltage source circuit 58 is connected in parallel across the damping winding 56 with the result that the capacity is reflected into the control winding 48. The capacity in the control winding 48 causes a phase shift of the current flowing in the control winding 48 and a resulting loss of torque. The inductor 186, thus, reflects a large inductance into the control winding 48 and cancels out the effect of the capacitor 128 without loading the control winding circuit. It should be appreciated, however, that the damping windings may alternatively be wound on slots other than the slots on which the control windings are wound and, accordingly, the indicator 186 may be eliminated from the circuit.

3. Motor Interrupting Subcircuit

The motor interrupting subcircuit 54 is shown in FIGS. 7 and 8 and has two specific functions. First, during opening and closing of the door it open circuits the motor control winding 48 for a predetermined time interval and simultaneously energizes the damping winding 56, thereby to permit the door 34 to be arrested under the exclusive control of the damping winding 56 and to cause the door 34 to move slowly into either its open or closed

position. Second, it prevents fingers from being crushed or injured between the free moving door 34 and the door jamb 24 as a result of a person stepping on the mat entrance side 42a during the predetermined time interval. Referring particularly to FIG. 7 in which the positions of the subcircuit relays, switches and contacts are shown when the door 34 is in its closed position, the subcircuit 54 comprises a pulse relay 190 which, when energized under the control of the door switches 170 and 174, causes a pair of contacts 192 serially connected to the center arm 96 of the bridge network 47 to be opened and a pair of contacts 194 serially connected directly between the D.C. terminal 144 and the damping winding to be closed. The subcircuit 54 is in a static condition, i.e., the relay 190 is set, when the contacts 172 of the door switch 170 and the contacts 176 of the door switch 174 are both closed. Then, when either of the contacts 172 or 176 are opened, the circuit 54 is operative to energize the relay 190 for a predetermined period of time during which the motor control winding 48 is open circulated and the damping winding is directly energized from the D.C. terminal 144. More specifically, the coil 190a of the relay 190 is connected in parallel with a serially connected rectifier 196 and a resistor 198, the parallel network being serially connected with a condenser 200. Both the parallel network and the condenser 200 are connected in parallel across the contacts 172 and 176 of the door switches 170, 174. The junction of the relay coil 190a and the resistor 198, identified as 202, is connected to the terminal 144 by a conductor 204 while the junction of the condenser plate 200b and one of the contacts 176, identified as 206, is serially connected through a current limiting resistor 208 to ground.

When the door is between the 30 degree and 60 degree door open positions, the subcircuit 54 is in its static condition. Specifically, the 175 volts of the D.C. terminal 144 is applied to each of the condenser plates 200a and 200b with the result that no current flows through relay winding 190a, condenser 200 and resistor 208. When the door reaches either its 30 degree or 60 degree open position, i.e., when it is 30 degrees adjacent to either its open or closed position, either one or the other of the contacts 172 or 176 is opened thereby to effect the removal of the 175 volts from the condenser plate 200b. Hence, because of the voltage potential across the capacitor 200, current flows through the relay winding 190 to charge the condenser 200, the current flow being from the terminal 144 through the relay winding 190a, the condenser 200, the resistor 208 and ground. No current flows through the parallel branch comprising the resistor 198 and the silicon rectifier 196 because of the high resistance offered by the rectifier 196. The time pulse relay 190 is thus energized by the condenser charging current and it remains energized for a predetermined time interval until the condenser approaches full charge and the condenser charging current is reduced to a value less than that necessary to hold up the relay 190.

The energization of the relay 190 effects the opening of the contacts 192 and the closure of the contacts 194. The opening of the contacts 192 open circuits a conductor 210 connected between the end 96b and the primary winding 98 and the closure of the contacts 194 completes a third energization circuit for the damping winding as follows (FIG. 8): the D.C. terminal 144, conductor 181, resistor 182, a conductor 212, contacts 194, a conductor 214, the inductor 186, the damping winding 56, power conductor 237, and ground. This latter circuit effectively bypasses the switches 170 and 174 and energizes the damping winding 56 irrespective of the position of the switch contacts 171, 172, 175 and 176. After the predetermined time interval the relay 190 is deenergized and the contacts 192 are closed and the contacts 194 are opened.

The circuit 54 is reset when the door moves between its 30 and 60 degree open positions and both the pair of contacts 172 and 176 are closed. The closure of the

contacts 172, 176 provides a discharging path for the condenser comprising the rectifier 196, the resistor 198, the contacts 172, 176 and the condenser 200. Only a small amount of current actually flows through the winding 190a since the resistance of the resistor 198 and the forward resistance of the rectifier 196 is one hundred times less than the resistance of the relay coil. Accordingly, only 1% of the total current flows through the winding 190a and this amount of current is inadequate to energize the relay 190. The condenser 200 is completely discharged and 175 volts is applied across the condenser plates 200a and 200b within one second which is less than the time required for the door to move between its 30 degree and 60 degree positions.

AUTOMATIC OPERATION—DOOR OPENING

Assuming that the operator is set to automatically open and close the door 34 on the left side of the doorway 22 and that the door is in its closed position, then the position of the control circuit switches, contacts and relays are as illustrated in FIG. 8. In the door closed position, the motor control winding 48 is deenergized and the motor damping winding 56 is energized under the control of the damping subcircuit 52. When a person walks through the entrance 20 and steps upon the mat entrance side 42a, the switch contacts 81 are closed thereby causing the energization of the operate relay 140, whereby the closure of its contacts 142 completes the first energizing circuit for the control relay 160. The control relay 160, however, is energized only in the event that the safety relay 150 is not energized and its contacts 154 are not opened. The energization of the control relay 160 causes the opening of the contacts 97a-100a, the opening of the contacts 162 thereby to deenergize the damping winding 56, the closure of the contacts 97a-104a, the closure of contacts 164 and the closure of contacts 166. The closure of the contacts 166 renders the safety relay contacts 154 ineffective while the closure of the contacts 164 connects the door position-sensitive switch 170 to the damping winding 56. The closure of the contacts 97a-104a causes the switch 97 to move from its voltage level 100 to the voltage level 104 on the winding 92 with the result that the network 47 is unbalanced and a voltage differential is developed across the center arm 96 of the potentiometer network 47 to provide a driving voltage through the stepup transformer to the motor control winding 48. Hence the servomechanism now seeks its door open "null position." The relative phase relationship of the voltage in the control winding 48 and the reference winding 60 is such that the door opens on the left side of the doorway 22 while the magnitude of the driving voltage (proportional to the difference between the slider 99 and switch 97 voltages) applied to the control winding 48 is of such high initial magnitude that the door promptly opens (see FIG. 10). The initially high driving voltage is linearly reduced to a substantially constant intermediate driving voltage within the first 2½ degrees of door movement under the control of the follower device 50, the slider 99 being moved from the voltage level 102 to the voltage level 105 under the influence of the cam 110. The intermediate driving voltage is applied to the control winding 48 between the 2½ degree to 87½ degree door open positions and effects an optimum opening speed of the door 34 between the 2½ degree to 60 degree door open position. Accordingly, the door is quickly opened and is moved at a speed to prevent a person from walking into the door when passing through the entrance 20 at a normal walking speed.

As the door reaches its 30 degree open position, the motor interrupting subcircuit 54 is set. Specifically, the camming portion 180a of the cam disengages the lever arm 174a of the door switch 174 thereby closing the contacts 176 and completing a condenser discharging circuit for the charged condenser 200 so that after the con-

denser 200 is discharged the 175 D.C. voltage is applied to both plates of the condenser 200.

As the door reaches its 60 degree open position, the camming portion 180a of the cam 180 engages the lever arm 170a of the door switch 170 thereby causing the contacts 172 to open and the contacts 171 to close. By the opening and closing of these contacts, both the damping and motor interrupting circuits 52 and 54 are operated, the damping circuit 52 being operated during the remaining 30 degrees of door travel and the motor interrupting circuit being operated during only a predetermined time interval. The closure of the contacts 171 completes the second energizing circuit for the damping winding 56 from the terminal 144, the conductor 181, resistor 182, conductor 183, the closed contacts 171, the socket 165, plug 167, conductor 184, contacts 164, conductor 185, inductor 186, the motor damping winding 56, the conductor 237, and ground. The energized damping winding 56 produces within the space occupied by the rotor a stationary magnetic field which produces, as described above, a resistance to rotation. On the other hand, the opening of the contacts 172 removes the D.C. voltage from the condenser plate 200b with the result that the time pulse relay 190 is energized by the charging condenser current. The operation of the time pulse relay 190 causes, first, the contacts 192 to open thereby to open circuit the center arm 96 of the network 47 to deenergize the motor control winding 48 and, second, the contacts 194 to close thereby to complete the third circuit for energizing the damping winding 56 independently of the door switches 170 and 174. The relay 190 is operated for a time interval equal to the LC time constant of the charging circuit, which time constant is of such duration, for example, three-tenths of a second, to permit the energized damping winding to work at full efficiency to slow down the door motion. As shown in FIG. 10, when the door is in its 60 degree open position, the motor control winding 48 is deenergized for the three-tenths of a second time interval and is then reenergized incident to deenergization of the time pulse relay 190. The motor damping winding 56, however, remains energized during the movement of the door between its 60 degree and 90 degree open position and thereafter while the door is in its door open position, as illustrated in FIG. 11.

The door moves at latching speed from a few degrees after the 60 degree open position to approximately 87½ degrees open position since both the motor control winding 48 and the damping winding 56 are energized. Between the 87½ degree and 90 degree open positions, the magnitude of the driving voltage progressively decreases (see FIG. 10) under the control of the follower device 50 and in particular the control cam 110. During this 2½ degree movement, the motor 44 rotates and the door 34 moves at a progressively slower speed as it approaches its 90 degree open position so that the resistive force offered by the energized damping winding, being dependent upon the speed of rotation of the motor, likewise progressively decreases. Actually, the motor 44 is slightly under-damped so that the door moves fairly promptly into its 90 degree open position with only a minimum of overshoot past the 90 degree open position.

Typically, a person moves from the mat entrance side 42a to the mat exit side 42b while the door is opening and only infrequently does he move into the mat exit side 42b after the door has completed its opening movement. In either case, the contacts 81 are opened thereby to deenergize the operate relay 140 and almost simultaneously the contacts 83 are closed thereby to complete an energization circuit for the safety relay 150. The relay 150 causes the closure of the contacts 152 to complete the second energization circuit for the control relay 160 for maintaining the control relay 160 operated entirely independently of the operate relay 140. If a time interval exists between the opening of the contacts 81 and the

closure of the contacts 83, the time delay condenser 173 discharges current through the control relay winding 160a, thereby to maintain the control relay 160 energized during the brief interval.

The door 34 remains in its open position and the servomechanism holds its door open "null position" as long as the person remains on the mat exit side 42b. This is true even though a person walks off the mat entrance side 42a while the person stands on the mat exit side 42b. It should be observed, as clearly shown in FIGS. 10 and 11, that in the door open position the control winding 48 is not energized while the damping winding 56 is energized and the potentiometer network is balanced with the switch 97 and the slider 99 at the same voltage levels, i.e., voltage levels 104 and 106, respectively. However, if the door 34 is manually moved toward its closed position or to a further opened position, the network 47 is unbalanced by the follower device 50 which causes the slider 99 to move away from the voltage level 106, thereby to create in the motor control winding a driving voltage having a polarity and magnitude to cause the door to be returned to its door open position. It should be noted that the greater the displacement of the door from its open position, the greater is the magnitude of the driving voltage applied to the motor control winding. This result is achieved because of the configuration of the cam 110 which unbalances the network 47 and develops a driving voltage having a magnitude proportional to the displacement of the door within 2½ degrees of its open position.

It has been determined from actual test that the operator 32 moves the door 34 from its closed to its 90 degree open position in 2.5 seconds. The door reaches the following open positions in the following total times: 2½ degree open position—.3 of a second; 60 degree open position—1.2 seconds; and 90 degree position—2.5 seconds. As indicated above, the motor control winding is de-energized for .3 of a second when the door reaches its 60 degree open position. Moreover, it has been found that the door is moved out of the path of a person walking through the entrance 20 quickly and dependably, and does not in any way interfere with or obstruct the person.

The door 34 is automatically closed by the person walking off of the mat exit side 42b and opening the contacts 83, assuming of course that no one else is standing on the mat entrance side 42a. The opening of the contacts 83 opens the energization circuit for the safety relay 150 with the result that the contacts 152 are opened and the second energization circuit for the control relay 160 is opened. Since the first energization circuit controlled by the control relay 160 was opened by the opening of the contacts 142 incident to deenergization of the operate relay, the control relay 160 is deenergized. The deenergization of the control relay 160 causes the contacts 97a-104a, contacts 164, and contacts 166 to open and the contacts 97a-100a and contacts 162 to close. The closing of contacts 162 serially connects the door switch 174 with the damping winding 56 while the opening of the contacts 164 disconnects the door switch 170 from the damping winding, thereby to effect the immediate deenergization of the damping winding 56 as shown in FIG. 11. The movement of the contact wiper 97a from the contacts 104a to the contacts 100a causes the switch 97 to move from the voltage level 104 back to its original voltage level 100 thereby to effect an unbalance of the potentiometer network 47 to produce a voltage differential across the center arm 96 and to develop a driving voltage for the motor control winding having such a phase as to move the door toward its closed position. Thus, the servomechanism now seeks its door closed "null position." The driving voltage has an initially high magnitude for promptly moving the door, which magnitude is linearly decreased to a substantially constant value at an 87½ degree open position as the slider 99 is moved from its voltage level 106 to its voltage level 105 under the control of the follower

device 50. The door moves at an optimum closing speed from its 87½ degree position to its 30 degree open position.

As the door passes its 60 degree open position, the motor interrupting subcircuit 54 is reset. Specifically, the camming portion 180a of the cam 180 disengages the lever arm 170a, thereby to open the contacts 171 and close the contacts 172. The opening of the contacts 171 performs no useful function since the contacts 164 are open under the control of the control relay 160. The closure of the contacts 172 completes a circuit for the capacitor discharging current from the capacitor 200, the rectifier 196, the resistance 198, the contacts 172, and closed contacts 176 so that after the capacitor 200 is discharged the D.C. voltage is supplied to both plates of the condenser 200.

When the door reaches its 30 degree open position, the camming portion 180a of the cam 180 engages the lever arm 174a thereby to effect the opening of the contacts 176 and the closure of the contacts 175. Again, both the damping subcircuit 52 and the motor interrupting subcircuit 54 are operated. In regard to the damping subcircuit 52, it is energized during the movement of the door from its 30 degree open to its closed position and thereafter as long as the door remains in its closed position, see FIG. 11. The closure of the contacts 175 completes the first energization circuit for the damping winding 56 from the terminal 144, conductor 181, resistor 182, conductor 183, contacts 175, socket 165, plug 167, a conductor 216, contacts 162, conductor 185, inductor 186, winding 56, power conductor 237, and ground. The energized damping winding produces within the space occupied by the rotor a stationary magnetic field which creates a resistive force to the rotation of the motor. Insofar as the motor interrupting circuit 54 is concerned, the opening of the contacts 176 causes charging current to flow from the terminal 144 through the winding 190a of the time pulse relay 190 into the condenser 200 so that the time pulse relay 190 is energized for approximately a three-tenths of a second time interval. The energization of the relay 190 effects the opening of the contacts 192 to open circuit the motor control winding 48 for the three-tenths of a second time interval (see FIG. 10) during which the motor 44 is exclusively damped by the damping subcircuit 52 and also effects the closure of the contacts 194 to complete the third energization circuit for the damping winding 56. The completion of the third energization circuit during the closing of the door performs an anti-guillotine function of protecting fingers against injury by inertia movement of the door through the doorway 22. Were it not for this third energization circuit, free inertia door movement would occur when the mat entrance contacts 81 are closed during the three-tenths of a second time interval since the first and second energization circuits would be opened. Specifically, the closure of the contacts 81 causes the control relay 160 to be operated thereby to disconnect the door switch 174 from the winding 56 by opening its contacts 162 and thereby open the first energization circuit and to serially connect the door switch 170 with the winding 56. However, at this 30 degree open position the contacts 171 of switch 170 are opened thereby to open the second energization circuit for the winding 56. Accordingly, no damping voltage is supplied to the damping winding 56 and no resistive force is applied on the motor; and because the energization circuit for the motor control winding 48 is opened, closing momentum of the door might cause the door to uncontrollably swing through the doorway 26. A person having knowledge of the latching speed of the door 34 would not expect this free momentum movement of the door and may seriously injure his fingers or limbs between the door 34 and the jamb 24. To avoid this type of door operation, the damping winding 56 is thus energized by the third energization circuit independent of the first and second energizing circuits when the motor

control winding 48 is deenergized during the three-tenths of a second time interval.

The door 34 travels at a reduced latching speed during movement of the door from a few degrees less than the 30 degree open position to its door closed position since both the control winding 48 and the damping winding 56 are energized. As the door moves between its 2½ degree open position to its closed position, the magnitude of the driving voltage applied to the motor control winding 48 progressively decreases under the control of the follower device 50. Accordingly, the damping of the motor 44 becomes progressively less as the speed of the motor decreases. The door, however, is slightly underdamped so that it moves fairly quickly into its door closed position with only a slight overshoot.

It should be appreciated, of course, that in the event the mat entrance contacts 81 are closed at any time during the closing of the door, the operate relay 140 and the control relay 160 will be immediately energized thereby to unbalance the potentiometer network 47 and cause the mechanism to seek its door open "null position." Accordingly, a driving voltage is applied to the motor control winding 48 having an opposite phase to the voltage applied during closing of the door, with the result that the motor reverses in direction and moves the door towards its open position.

The door is maintained in its closed position under the control of the servomechanism which holds its door closed "null position." Similar to when the door is in its open position, the motor control winding 48 is deenergized and the damping winding 56 is energized (see FIGS. 10 and 11) as long as the door remains in its closed position and the system is turned on. If, for example, a sudden gust or draft moves the door off its closed position, the follower device 50 unbalances the potentiometer network 47 to provide a driving voltage having the necessary phase relative to the reference voltage winding 60 to move the door back to its closed position. It should be noted that the greater the displacement of the door from its open position, the greater is the magnitude of the driving voltage applied to the motor control winding. This result is achieved because of the configuration of the cam 110 which unbalances the network 47 and develops a driving voltage having a magnitude proportional to the displacement of the door within 2½ degrees of its closed position.

AUTOMATIC OPERATION—SAFETY OPERATION

The electric door operator 34 is characterized by several safety features which practically eliminate the possibility of injury to persons walking through or moving adjacent to the entrance 20.

1. Door Closed—Person on Mat Exit Side

In the event that a person steps onto the mat entrance side 42a when the door is in its closed position while another person is standing on the mat exit side 42b, the door does not open and will not open while the person remains standing on the mat exit side 42b. Accordingly, an inattentive individual standing on the mat exit side 42b is afforded protection against being struck by the moving door. Specifically and referring to FIG. 8, when the person first stands on the mat exit side 42b, the switch contacts 83 are closed thereby to energize the safety relay 150. The energization of the safety relay causes contacts 154 to be opened thereby to open the first energizing circuit, including the contacts 149 of the operate relay 140, for the control relay 160 and prevent the energization of the control relay 160. A person may walk on and off the mat entrance side 42a without opening the door and as long as the person stands on the mat exit side 42b the door remains closed. Of course, once the person steps off the mat exit side 42b the safety relay 150 is deenergized and the contacts 154 are closed. If either a person is standing on the mat entrance side 42a or a person thereafter steps on the mat entrance side 42a, the

operate relay 140 is energized to complete the first energization circuit for the control relay 160 thereby to cause the servomechanism to seek its door open "null position" and open the door.

5 Although the electric door operator 32 does not automatically open the door 34 when someone is standing on the mat exit side 42b, the door 34 nevertheless may be manually opened by a person walking through the entrance 20. Accordingly, the entrance 20 is not rendered entirely inoperative and the door 34 is operated under the manual control and care of a person passing through the entrance 20.

2. Door Opened—Person on Mat Exit Side

15 The door 34 remains in its open position as long as a person stands on the mat exit side 42b and holds the contacts 83 closed to complete the energization circuit for the safety relay 150. The energized safety relay 150 keeps the contacts 152 closed to complete the second energization circuit for the control relay 160, and the servomechanism holds its door open "null position." Irrespective of persons walking on and off of the mat entrance side 42a, the servomechanism holds its door open "null position" and the door remains in its open position as long as the person remains standing on the mat exit side 42b.

20 The door 34 also remains in its open position when persons alternately stand on the mat entrance side 42a and the mat exit side 42b provided that the time lapse between the closure of the contacts 81 and 83 is less than quarter of a second time delay occasioned by the charge on the capacitor 173 discharging through the relay winding 160a. Hence, the control relay 160 is continuously energized even though there are short time intervals when 25 both the mat contacts 81 and 83 are opened.

3. Door Closing—Person on Mat Exit Side

25 In the event that the door 34 is being closed automatically under the control of the servomechanism and a person intentionally or inadvertently stands on the mat exit side 42b, the door is immediately stopped thereby to prevent the person from being struck by the door moving at its full power. Specifically, during closing of the door all of the relays 140, 150 and 160 are deenergized and a driving voltage is supplied by the unbalanced network 47 to the control winding 48 as a result of the switch 97 being moved to the voltage level 100 incident to deenergization of the control relay 160. However, when a person stands on the mat exit side 42b during the closing of the door, the motor is simultaneously deenergized and damped to effect the immediate stopping of the door. Specifically, incident to closure of the mat exit contacts 30 83, a circuit is completed for energizing the safety relay 150 which causes the closure of the contacts 152 and 153 and the opening of contacts 154 and 156. The opening 35 of the contacts 156 opens the circuit between the end 96a of the arm 96 and the voltage level 100 on the winding 92, thereby open circuiting the center arm of the potentiometer network 47 and removing the driving voltage from the motor control winding 48. The closure of the contacts 158 completes a fourth energization circuit for the damping winding as follows: from the D.C. terminal 144, the conductor 181, resistor 182, conductor 183, a conductor 218, contacts 158, conductor 220, conductor 216, contacts 162, conductor 185, inductor 186, damping winding 56, power conductor 237, and ground. Thus, the motor control winding 48 is deenergized and the motor damping winding 56 is simultaneously energized to cause the door 30 to instantaneously stop. Furthermore, the door remains in its stopped position intermediate the door open and closed position under the control of the safety relay 150 as long as the person remains on the mat exit side 42b. If while the person stands on the mat exit side 42b another person stands on the mat entrance side 42a to energize the operate relay 140, the door remains in its arrested position since the energization circuit, 40 45 50 55 60 65 70 75

including the operate relay contacts 149, is open circuited by the opening of the safety relay contacts 154. Accordingly, the door 34 does not move even though persons walk on and off the mat entrance side 42a.

When the person steps off of the mat exit side 42b, the contacts 83 are opened and the safety relay 150 is energized whereby the contacts 152 and 158 are opened while the contacts 154 and 156 are closed. The opening of the contacts 158 simultaneously opens the fourth energizing circuit for the motor damping winding 56 to remove the resistive and retarding force from the motor 44. The closure of the contacts 156 closes the previously opened circuit between the end 96a of the arm and the voltage level 100 of the winding 92 thereby applying a voltage differential across the center arm 96 of the potentiometer network 47 so that once again a driving voltage is applied to the motor control winding 48. With the motor 44 reenergized, the servomechanism again seeks its door closed "null position" and the door 34 is returned to its closed position under the control of the potentiometer network 47 and the follower device 50.

CLOSER OPERATION

The electric door operator 32 may be manually conditioned to operate as a conventional double-acting door closer, i.e., to automatically return the door 34 to its closed position after the door is manually opened on either side of the doorway 22, by disconnecting the mat entrance and exit switches 81 and 83 from the treadle mat subcircuit 49 to render the control relay 160 ineffective. Hence, irrespective of actuation of the mat switches by a person walking through the entrance 20, the control relay 160 remains deenergized so that the switch 97 does not unbalance the potentiometer network 47. In this connection, a switch 222 is mounted in the jamb 24 of the doorway and is operable to open a pair of contacts 224 in the conductor 145. The opening of the contacts 224, thus, opens the energization circuits for both the operate relay 140 and safety relay 150 so that even though the mat switch contacts 81 and 83 are closed by a person standing on the mat 42 the control relay 160 remains deenergized. With the control relay 160 rendered ineffective, the switch 97 at the end 96a of the center arm 96 of the potentiometer network 47 remains at the voltage level 100 as a person walks through the entrance 20 with the result that the network 47 is not unbalanced by the switch 97. However, in response to the manual movement of the door 34 by a person walking through the entrance 20, the follower device 50 effects an unbalance in the network 47. Specifically, the cam 110 is rotated thereby to move the slider 99 from the voltage level 102 to another voltage level either toward the voltage level 101 if the door is opened on the right side of the doorway 22 or toward the voltage level 105 if the door is opened on the left side of the doorway 22. Thus, the slider 99, instead of the switch 97, effects an unbalance in the potentiometer network 47 and causes a driving voltage to be applied to the motor control winding 48 to urge the door towards its closed position.

It will be appreciated that a person manually opening the door must overcome the motor torque developed as a result of unbalancing the network 47 and must also overcome the resistive force offered by the energized damping winding 56. As described above, the motor damping winding 56 is energized when the door 34 is closed and offers a resistive force to the motor if the door 34 is moved away from its closed position. Accordingly, when the door 34 is manually opened on the left side of the doorway 22 as viewed in FIG. 1 (opening movement A in FIG. 9), the motor damping winding 56 remains energized to offer a resistive force directly proportional to the speed of the door opening movement (see FIG. 16). This result obtains since between the door closed and 30 degree open position the cam 180 maintains the contacts 175 closed to complete the first energization circuit for

the damping winding 56. This first energizing circuit is not opened by the contacts 162 as is normally the case when the door is automatically opened, since the control relay 160 is not energized by the treadle mat subcircuit 49. As the door reaches its 30 degree open position, the cam 180 disengages the switch 174 to effect the closure of the contacts 176 and the opening of the contacts 175 with the result that the first energization circuit is open circuited and the motor damping winding 56 is deenergized (see FIG. 16). From the 30 degree door open position to 90 degree door open position, the motor damping winding 56 is deenergized and no damping resistive force opposes the manual door opening force.

The magnitude of the driving voltage supplied to the motor control winding 48, the switch voltage 97 and the slider voltage 99, as the door is manually opened 80 degrees and automatically closed on the right side of the doorway 22, is illustrated in FIG. 15. During initial opening movement of the door 34, the cam 110 rotates counterclockwise and the follower pin 114 moves along the groove portion 132 thereby to displace the follower bar 116 and move the slider 99 from the voltage level 102 toward the voltage level 105. The movement of the slider 99 effects an unbalance of the potentiometer network 47 thereby to produce in the motor control winding 48 a driving voltage having such a phase as to urge the motor to return the door to its closed position. When the door reaches its 2½ degree open position, the follower pin 114 moves into the groove portion 133 and the slider 99 reaches the voltage level 105. The slider remains at the voltage level 105 until the door 34 reaches the 87½ degree open position where the follower pin 114 moves into the groove path 134 and the slider 99 moves from the voltage level 105 toward the voltage level 106, the driving voltage being proportional to the difference between the switch and the slider voltages.

In normal usage, a person manually pushes the door to a 70 or 80 degree open position and as he passes by the door he releases it. Once the manual door opening force is removed, the driving voltage becomes effective to automatically close the door (closing movement B in FIG. 9). Actually, the servomechanism now seeks its door closed "null position." The driving voltage as shown in FIG. 15 remains at a value proportional to the difference between the switch 97 and the slider 99 voltages, i.e., voltage level 100 and voltage level 105, during closing of the door from its 80 degree open to 30 degree open position and effects an optimum door closing speed. When the door 34 reaches its 30 degree open position, the motor interrupting subcircuit 54 and the damping subcircuit 52 are operated such that the motor control winding 48 is temporarily interrupted for a predetermined time interval (see FIG. 15) and the damping winding 56 is energized during the last 30 degree travel of the door (see FIG. 16). Thus, the speed of the door is changed from an optimum closing speed to a slow latching speed in exactly the identical manner as described above in connection with the automatic operation of the door.

In the event that the door is manually opened on the right side of the doorway 22 as viewed in FIG. 1 (opening movement C in FIG. 9), both a damping resistive force and an opposing motor force act in opposition to the manual opening force. Specifically, the cam 110 rotates in a clockwise direction to cause the follower pin 114 to travel in the groove portion 131 and to move the slider 99 from the voltage level 102 toward voltage level 101. After the door is opened 2½ degrees the follower pin 114 moves into the groove portion 130 and the slider 99 reaches the voltage level 101. Thereafter the slider 99 remains at the voltage level 101 and the switch 97 remains at voltage level 100 as the door opens to its 90 degree open position so that a constant driving voltage is supplied to the control winding 48 (see FIG. 15). The resultant driving voltage 48 is of opposite phase to the driving voltage obtained during opening movement of

the door on the left side of the doorway 22 and urges the door to return to its closed position. In addition to the opposing motor force, the damping resistive force is applied to the motor 44 during the first 30 degree opening movement of the door (see FIG. 16). Similar to the door opening on the right side of the doorway 22, the motor damping winding 56 remains energized until the door reaches its 30 degree open position wherein the 60 degree peripheral cam portion 180a of the cam 180 disengages the switch 174 thereby to open the first energizing circuit for the motor damping winding 56. Accordingly, from the 30 degree position to its 90 degree open position, the only force acting in opposition to the manual door opening force is the opposing force of the motor.

After the door is manually moved to its maximum open position, for example, an 80 degree open position, it is released whereupon the driving voltage becomes effective to automatically return the door to its closed position (closing movement D in FIG. 9). During closing movement, the servomechanism seeks its door closed "null position." The magnitude of the driving voltage between the 80 degree and 30 degree open position as illustrated in FIG. 15 is constant and is proportional to the difference between the slider 99 and switch 97 voltages, i.e., voltage level 100 and voltage level 101, thereby providing an optimum closing speed for the door. As the door reaches its 30 degree open position during its closing movement, the motor interrupting subcircuit 54 and the damping subcircuit 52 are operated with the result that the motor control winding 48 is temporarily interrupted (see FIG. 15) and the damping winding is energized during the last 30 degrees of door travel and as long as the door remains in its closed position (see FIG. 16). Accordingly, the door speed changes from its optimum closing speed to its latching speed in the same manner as described above in connection with automatic operation of the door.

HOLD OPEN OPERATION

It is often desirable to have the door 34 remain in a continuously open position, for example, when deliveries are being made, or when it is desired to ventilate the interior of the building. The electric door operator 32 is adapted to be conditioned to hold the door in its open position with the use of no more power than is required to hold the door in its door closed position. To this end, a hold open switch 226 is mounted in the jamb 24 and is manually operable to close a pair of contacts 228 for completing a second energization circuit for the operate relay 140 as follows: from ground, a conductor 230, contacts 228, a conductor 232, the conductor 146, the winding 140a, conductor 147, the 12 volt A.C. source 143, the conductor 148, and to ground. It will be observed that the circuit comprising conductor 230, the contacts 228, and the conductor 232 is in parallel with the mat entrance contacts 81 so that when the contacts 228 are manually closed, the operate relay 140 is energized irrespective of the opened mat entrance contacts 81. The energized operate relay 140 effects the energization of the control relay 160 with the result that the servomechanism seeks its door open "null position" and the door is opened in the same manner as when a person steps on the mat entrance side 42a. The servomechanism holds its door open "null position" and retains the door in its open position as long as the switch contacts 228 are closed. If a force, e.g., a force resulting from wind gusts, children, animals or the like, moves the door from its open position, the potentiometer network 47 becomes unbalanced and develops a driving voltage which has the proper phase to return the door to its open position, in the same manner as described above. It will be appreciated that even though the mat entrance contacts 81 and the mat exit contacts 83 are closed and opened during the movement of traffic through the doorway 22, the door remains closed under the direct control of the operate relay 140 and the control relay 160.

If it is desired to condition the electric door operator for automatic operation, the switch contacts 228 are opened to cause the deenergization of the operate relay 140 and the control relay 160 with the result that the servomechanism seeks its door closed "null position" and returns the door to its closed position as described above.

PANIC OPERATION

The entrance 20 accommodates single lane traffic moving into a building, i.e., from the right side to the left side of the doorway 22 and, to this end, the operator 32 is set to automatically open and close the door 34 on the left side of the doorway 22. In order to permit people to pass out of the building, i.e., from the left to the right side of the doorway 22, during an emergency, for example, a fire or the like, it is extremely important that the people may panic or manually open the door on the right side of the doorway 22 without any interference from the electric door operator. Moreover, it is preferable that the door be panic opened without breaking any door positioning means or without requiring any panic device to be reset or readjusted by a serviceman or the like. In accordance with a feature of the present invention, the electric door operator 32 is so designed that it permits panic or manual opening of the door and then automatically returns the door to its closed position under the control of the servomechanism.

More specifically, assuming the door 34 is closed and a person starts to walk through the entrance in a direction opposite to the normal flow of traffic, he first steps on the mat exit side 42b to close the switch contacts 83. The closure of the contacts 83 effects the energization of the safety relay 150 with the attendant opening of the contacts 154 and 156. The opening of the contacts 154 open circuits the first energization circuit for the control relay 160 thereby assuring that the switch 97 remains at the voltage level 100. The opening of the contacts 156 opens the circuit between the end 96a of the center arm 96 and the winding 92, thereby to assure that no driving voltage is supplied to the motor control winding 48 while a person stands on the mat exit side 42b. As the person passes through the entrance 20, he manually opens the door on the right side of the doorway 22 (opening movement C in FIG. 9). After 1½ or 2 degrees of opening movement, a panic safety switch 240 (see FIGS. 2, 8 and 17) is opened to open circuit the energization circuit for the operate relay 140 and hence to render the control relay 160 inoperative, as described below. The panic door opening movement also causes the cam 110 to rotate clockwise to move the follower pin 114 into the groove portion 131 and to move the slider 99 from the voltage level 102 toward the voltage level 101. When the door reaches its 2½ degree open position, the follower pin 114 reaches the groove portion 130 and the slider 99 moves to the voltage level 101 where it remains during the balance of the door opening movement. Although the slider 99 and switch 97 are at different voltage levels and the potentiometer network 47 is unbalanced, no driving voltage is supplied to the motor control winding 48 since the center arm 96 of the network 47 is open circuited by the opened contacts 156. The magnitudes of the driving voltage, slider voltage and switch voltage are illustrated in FIG. 13 as the door is panic opened to an 80 degree open position and automatically returned to its closed position.

It should be realized that since the cam portion 180a of the cam 180 engages the switch 174 the damping winding 56 remains energized throughout the first 30 degree opening movement of the door so that a resistive damping force proportional to the manual speed of the door is applied to the motor 44 (see FIG. 14). The panic operation differs from the closer operation in that during the closer operation both a damping resistive force and rotative motor force oppose the manual opening force while in the panic operation only the damping resistive force

opposes the manual opening force during the initial manual opening of the door.

The panic safety switch 240, as illustrated in FIG. 17, is operatively associated with the follower bar 116. Specifically, the switch 240 comprises a limit switch having a plunger 241 actuated by a follower lever 242 pivotally supported from the body of the switch. The lever has a roller 242a for engagement with a camming surface 243 defined on the elongated bar 116. When the servomechanism is at its door closed "null position," the roller 242a is located adjacent to the right end, as illustrated in FIG. 17, of a lower recess camming portion 243a on the bar 116. Incident to automatic opening and closing of the door, the rod 116 reciprocates and the lower recess portion 243a moves back and forth so that the roller dwells in the portion 243a without actuating the plunger 241 and does not engage the surface portions 243b or 243c defined on opposite sides of the lower recess portion 243. However, with the above described panic opening of the door and the attendant movement of the follower pin 114 along the groove portion 131, the elongated bar 116 and the recess 243a move to the left, with the result that the roller 242a is cammed upwardly onto the surface 243c of the bar 116, thereby to actuate the plunger 241 and open the switch 240. The recess 243a of the bar 116 is so configured and the switch 240 is so related relative to the recess 243a that the switch is opened when the door has been moved 1½ or 2 degrees in the direction of panic movement and remains open during the balance of the panic opening movement until the door returns to the 1½ or 2 degree panic open position. As shown in FIGS. 8 and 17, the switch 240 is located in the energization circuit for the operate relay 140 so that while the switch is opened the operate relay 140 and the control relay 160 are rendered ineffective. Thus, the switch 97a remains on the voltage level 100 irrespective of actuation of the treadle mat switches by the person walking through the doorway to panic operate the door. It will be appreciated that if the door is set to automatically open and close on the right-hand side of the doorway, in contrast to the above described automatic operation, then the follower pin 114 is located in the door closed "null position" 138 on the cam 110 and the roller 242a is located adjacent to the left end of the recess 243a. Then, panic opening of the door to the left side of the doorway causes the pin 114 to move along the groove 135 and the roller 242a to be cammed upwardly by the surface 243b, thereby to open the switch 240.

Returning now to the description of the panic opening of the door, when the person steps off the mat exit side 42b onto the mat entrance side 42a, the mat exit contacts 83 are opened and the entrance mat contacts 81 are closed thereby to effect the deenergization of the safety relay 150. At this moment, the door is in an approximate 40 degree open position. As a result of the deenergization of the safety relay 150, the contacts 156 close to close the previously open circuited center arm 96 of the potentiometer network 47. At this moment, the potentiometer network 47 is unbalanced because of the slider 99 being at voltage level 101 and the switch 97a being at voltage level 100 and the control winding 48 is supplied with a driving voltage having a phase to return the door 34 to its closed position. Hence, when the person steps off the exit mat side 42b and onto the entrance mat side 42a, the motor 44 is energized to offer a force opposing the opening movement of the door. However, the magnitude of the opposing force is easily overcome by the manual opening force and does not interfere with or obstruct panic opening of the door.

Were it not for the safety switch 240, the control relay 160 would be energized incident to closure of the entrance mat contacts 81 with the result that the switch contact 97a would disengage contact 100a and engage contact 104a, thereby causing the switch 97 to move from the voltage level 100 to the voltage level 104 with the result that the potentiometer network 47 would be further un-

balanced. At this precise moment, a voltage differential would exist between the ends 96a and 96b of the center arm 96 equal to the voltage difference between the voltage level 104 and the voltage level 101. The magnitude of the driving voltage would be one and a half times greater than the magnitude of the actual driving voltage.

Once the person steps off the mat entrance side 42a and releases the door in its maximum open position, for example, an 80 degree open position, the servomechanism seeks its door closed "null position" and returns the door to its closed position in exactly the same manner as described above in connection with the automatic operation and door closer operation of the door operator 32. As described above, when the door reaches its 30 degree open position, the motor interrupting subcircuit 54 and the damping subcircuit 52 are operated, thereby to temporarily open circuit the motor control winding 48 and to energize the motor damping winding 56 during the last 30 degree travel of the door.

It will be appreciated that the door may be panic operated without rupturing any panic "break away" devices, thereby eliminating the services of a repairman or the like. Furthermore, by the present invention, the door is automatically returned to its door closed position after panic opening and is automatically opened and closed thereafter under the control of the door operator without manual attention of any kind.

In order to prevent the door from being panic opened on the right side of the doorway 22 beyond a designated point, suitable stops (not shown) may be provided so that whenever the door reaches its maximum open position the opening movement of the door will be positively arrested. Thus, disengagement of the follower pin 114 from the groove portion 130 of the cam 110 is prevented and possible injury to the follower device 50 is obviated.

REVERSING AUTOMATIC OPERATION

As described above, the electric door operator 40 is selectively single-acting in its operation and is adapted to be set to open and close either on the left side of the doorway 22 (opening movement A and closing movement B in FIG. 9) or on the right side of the doorway 22 (opening movement C and closing movement D in FIG. 9). The direction of door opening and closing is dependent upon the type of connector plug 167 inserted within the socket 165 and, more particularly, the type of circuit connections included in the plug 167. Specifically, if it is desired to have the door open on the right side of the doorway 22 instead of the left side, as illustrated in FIG. 1 and described above, then a plug 267 is substituted for the plug 167 and the position of the treadle mat 42 is reversed so that the mat entrance side 42a is on the left side of the doorway and the mat exit side 42b is on the right side of the doorway. In order to change plugs, the on-off switch 139 is opened thereby to deenergize the entire system. The door is then moved to its 90 degree open position on the left of the doorway and disconnected from the upper door pivot 36. The operator is removed from the transom tube and thereafter, the plug 167 is removed, the plug 267 is inserted into the socket 165, and the on-off switch 139 closed. Even though the door pivot is rotated 90 degrees the different connections within the plug 267 do not effect an unbalance in the network 47, as would be the case if the plug 167 were connected in the socket, since the switch 97, which was formerly at the voltage level 100, is now connected to the voltage level 104, while the slider 99, which was formerly at the voltage level 102, is now at voltage level 106 because of the manual rotation of the door pivot 36. Thus, since the switch 97 and the slider 99 are at the same voltage levels, the potentiometer network is not unbalanced and the slider 99 remains at the voltage level 100 which would not be the case when the plug 167 is connected to the socket 165. Hence, while the switch 97 and the slider 99 were formerly at the voltage level 100 and 102, respectively, in

the door closed position, they are now at the voltage level 104 and 106, respectively, in the new door closed position. The hold open switch 226 is then closed so that the door pivot rotates 90 degrees into its door open position and then the on-off switch 139 is opened. Thereafter, the door is oriented in its open position and then mounted to the door pivot. Finally, the on-off switch 139 is closed and the hold open switch 226 is opened, whereby the door is returned to its closed position under the control of the servomechanism. Now when a person walks from the left side to the right side of the doorway, i.e., opposite to that described above, and steps on the mat entrance side 42a which is now on the left side of the doorway, the energized control relay moves the switch 97 from the voltage level 104 to 100, thereby supplying to the motor control winding 48 a driving voltage having such a phase as to move the door to the right of the doorway and not to the left.

Inasmuch as the door pivot 36 was rotated 90 degrees prior to the exchange of plugs, the cam 180 is also rotated so that the middle of the cam portion 180a engages the switch 170 instead of the switch 174. Whereas as the switch 170 was formerly engaged by the cam 180 between the 60 degree to 90 degree open positions of the door, the switch 170 now is engaged by the cam 180 between the door closed position and the 30 degree door open position. Similarly, whereas the switch 174 was engaged by the cam 180 between the door closed position and the 30 degree door open position, the switch 174 is now engaged by the cam 180 between the 60 degree to 90 degree open positions of the door. Accordingly, even though the door 34 opens on the left side of the doorway 22, the door 34 is damped when it reaches a position 30 degrees adjacent to its open and closed positions.

Considering now the follower device 50 and specifically the location of the follower pin 114 relative to the cam 110, when the door pivot 36 is rotated 90 degrees, the follower pin 114 moves from the point 137 along the groove portions 132, 133, 134 to the point 138 to its new door closed position. Therefore, when the door 34 is automatically opened on the right side of the doorway 22, the follower pin 114 moves from the point 138 along the groove portions 134, 133 and 132 to the point 137 while the slider 99 moves from voltage level 106 to voltage level 104. When the door is automatically closed on the right side of the doorway, the pin 114 moves back along the groove portions 132, 133 and 134 while the slider moves from voltage level 104 to voltage level 106. In both cases, the phase of the driving voltage is opposite to the phase of the driving voltage developed to open and close the door on the left side of the doorway. Furthermore, it will be appreciated that as the follower pin moves from the point 137 to the point 138, the bar 116 moves from left to right (as viewed in FIG. 17) thereby to position the left end of the recess 243a adjacent to the roller 242a of the panic safety switch 240.

In the event that the door is panic operated to the left of the doorway 22 (opening movement A in FIG. 9), the network 47 is unbalanced by the follower device 50 in the same manner as when the operator is set to automatically open and close the door 34 on the left side of the doorway. However, in contrast to the above described panic operation, the follower pin 114 moves along the groove portions 135 and 136 and causes the slider 99 to move from voltage level 106 to voltage level 107, thereby developing a driving voltage for returning the door to its closed position after manual release of the door. In addition, during the above described panic movement of the door, the roller 242a of the panic safety switch 240 is cammed upwardly onto the surface 243b, in contrast with the surface 243c, to open circuit the operate relay 140 and prevent the subsequent energization of the control relay 160 when the person steps from

the mat exit side, located on the right side of the doorway as viewed in FIG. 1, to the mat entrance side, located on the left side of the doorway.

The operator 32 when set to open the door on the right side of the doorway 22 also functions as a double-acting door closer when the switch 222 is closed. The door closer operation is identical to the above described closer operation except that when the door is manually opened on the left side of the doorway (opening movement A in FIG. 9), the pin 114 moves along groove portions 135 and 136 to cause the slider to move from voltage level 106 to voltage level 107 and when the door is opened on the right side of the doorway (opening movement C in FIG. 9), the pin moves along groove portions 134 and 133 to cause the slider to move from voltage level 106 to voltage level 105. In either case, in response to manual opening of the door the network 47 is unbalanced by the follower device 50 to produce a driving voltage for returning the door to its closed position.

MODIFICATION FOR DOOR SIZE

It will be appreciated that the size and type of entrance and in particular the size and type of door varies with the demands of the installation. Generally, large sized doors are somewhat heavier and have a higher inertia than the smaller doors, with the result that the large doors provide a different damping problem than the small doors. To this end, the plugs 167 and 267 and in addition plugs 367 and 467 are selectively used to control the magnitude of the damping current in the damping winding and, hence, the magnitude of the damping resistive force. The plug 367 has an electrical circuit for causing the door to open and close on the left side of the doorway, similar to the plug 167, and the plug 467 has an electrical circuit for causing the door to open and close on the right side of the doorway, similar to plug 267. The plugs 367 and 467 differ from the plugs 167 and 267, respectively, in that each is provided with a conductor 234 which interconnects conductors 236 and 238 when the plug is inserted into the socket 165. Particularly, the plugs 367 and 467 effectively short out the current limiting resistor 182 from the energization circuit for the damping winding, with the result that the damping circuit resistance is decreased so that more current flows through the motor damping winding 56. With a higher current flowing through the damping winding 56, a stronger stationary magnetic field and a greater resistive damping force is developed.

From the foregoing description, it will be appreciated that the direction of automatic opening of the door and/or the magnitude of the resistive damping force can be selected by choosing a particular one of the available plugs. Accordingly, the operator 32 has greater flexibility and its operation may be readily altered by the simple expediency of changing plugs.

CONCEALED OPERATOR

The automatic entrance 20 is so designed so that all of the operating components of the servomechanism and the components of the electrical control circuit are enclosed within the entrance 20. Specifically, the mechanical and electrical components of the servomechanism are mounted on and supported from a lower base plate 28a of the transom 28 to facilitate installation and exchange. In installation, the servomechanism components and most of the electrical circuit components are first mounted on the plate 28a and then the plate 28a is manually nested within the vertical walls of the transom tube 28 to be secured thereto by appropriate fasteners (not shown). The balance of the components of the electrical circuit, including conductors, are located within the jamb 24 and serve to connect the switches 139, 222, and 226 to the servomechanism components, the A.C. power supply 63, and the mat 42. It should be noted that by this arrangement no electrical

wiring or electrical wiring components are visible. The outlet from the power supply 63 can be located so that it is enclosed by the top or bottom of the jamb 24. Accordingly, the entrance 20 is clean in appearance and does not have motors, relays, gears and wiring disposed externally of the jambs 24 and 26 or the transom tube. Alternatively, the outlet can take the form of a socket onto which an external cord and plug arrangement of the door operator is inserted and, in this embodiment, the cord and plug arrangement might be visible.

ADDITIONAL EMBODIMENTS

Another embodiment of the present invention includes a modified potentiometer network, shown in FIG. 5. The modified network 247 differs principally from the potentiometer network 47 in that it embodies a single potentiometer network rather than the A.C. bridge network illustrated in FIG. 4. Specifically, the potentiometer circuit 247 embodies a single transformer winding 258 which is energized by and connected across a suitable A.C. source 263. The potentiometer network 247 includes, similar to the network 47, a follower mechanism 250 for moving a slider 299 between voltage levels 301, 302, 305, 306 and 307, these voltage levels corresponding to the voltage levels 101, 102, 105, 106 and 107 on the winding 94 of the A.C. bridge network 47. The slider 299, in contrast to the slider 99, is connected by a conductor 300 directly to one end 248a of the motor control winding 248. The other end 248b of the motor control winding 248 is connected to a switch 297, similar to the switch 97 in the network 47, which is actuated under the control of a control relay 260, identical in structure and operation to the control relay 160. The switch 297 includes a contact wiper 297a movable between contacts 300a and 304a for the purpose of connecting the end 248b of the winding 248 to one of two voltage levels 300-304 on the winding 248, the voltage levels 300 and 304 being respectively equal to the voltage levels 302 and 306. When the door is closed the wiper switch 297 engages the contact 300a thereby to connect the switch to the voltage level 300 while the slider 299 is at the voltage level 302. Accordingly, no current flows through the motor control winding 248 and the door remains in its closed position. However, when the mat entrance switch contacts are closed by a person stepping on the mat, the control relay 260 is energized and the switch wiper 297 engages the contact 304a thereby to connect the end 248b of the control winding 248 directly to the voltage level 304. Since the voltage levels 302 and 304 are unequal, a voltage difference is developed across the motor control winding 248. As described above, the energized motor drives the door under the control of the follower device 250 to its open position wherein the slider 299 moves to the voltage level 306. It will be appreciated that in the modified network 247 illustrated in FIG. 5 a single transformer winding is used instead of both a reference autotransformer and a Variac and that the step-up transformer 95-98 is eliminated by connecting the motor control winding 248 directly to the switch 297 and the slider 299.

A further embodiment of the present invention includes yet a further modified potentiometer network 347. As shown in FIG. 6 the network 347 differs principally from the potentiometer network 247 in that a slider 399 is adapted to be moved along a band of contacts 349 connected by suitable conductors 351 to spaced points on a single transformer winding 358, instead of being movable along the winding itself. By this arrangement, the elongated follower bar 116 and a rack and gear arrangement 118, 120 may be eliminated since there is a need for only a relatively short and compact slider arrangement. The slider 399 is preferably located immediately adjacent to the control cam, similar to the control cam 110, and accordingly may be spaced a substantial distance from the transformer winding 358. In all other constructional

and operational respects, the potentiometer network 347 is identical to the potentiometer network 247.

While the present invention has been described in connection with the details of particular embodiments thereof, it should be understood that these details are not intended to be limitative of the invention since many modifications will be readily apparent to those skilled in this art and it is, therefore, contemplated in the accompanying claims to cover any such modifications as fall within the true spirit and scope of the invention.

What is claimed as new and desired to be secured by United States Letters Patent is:

1. An electric door operator for a door, said operator comprising a servomotor for moving said door between open and closed position, said servomotor having a control winding and having a retarding winding adapted to be energized by a power source, means for developing a driving voltage to energize said control winding, and a control circuit including time delay means and a door position sensitive switch operable when said door reaches a predetermined point in its travel towards its closed position to actuate said time delay means for effecting temporary removal of said driving voltage from said control winding and to connect said retarding winding to said power source, thereby to cause a rapid slowing down of the moving door member, said time delay means operating after a predetermined time interval to cause re-energization of said control winding with said driving voltage so that in cooperation with the energized retarding winding the door member is moved toward its closed position at a reduced speed.

2. An automatic operator for moving a door from a closed position to an open position, said operator comprising servomechanism including a single servomotor for moving the door between said positions, electrical circuit means automatically operated in response to movement of traffic adjacent the door for developing a first electrical signal corresponding to the open position of the door, feedback means operated simultaneously with the movement of said door for developing a second electrical signal varying during the opening of the door from a first level representing the closed position of the door to a second level equal to said first signal, and means for comparing said first and second signals to produce in response to the difference therebetween a control signal for operating said servomechanism to drive the door in a direction to move it from its closed position to its open position.

3. The apparatus defined by claim 2 wherein the feedback means is so constructed and arranged that the control signal developed varies non-linearly and has an initially high level for a predetermined period to overcome the inertia of the door to move it from its closed position and a substantially constant intermediate level for moving the door at optimum speed towards its open position, which intermediate level decreases to zero when the door reaches the open position.

4. An operator for automatically opening and closing a door, said operator comprising a servomechanism including a single servomotor operably connected to the door, electrical circuit means automatically operated by movement of traffic in approaching and passing through the door for developing a first electrical signal which changes abruptly from a first level representing the closed position of the door to a second level representing the open position of the door when the traffic approaches the door and then returns to said first level when the traffic moves through and beyond the door, feedback means operably connected to and driven simultaneously with the door for developing a second electrical signal which varies during the door movement, both during opening and closing, and means for comparing both of said signals and for producing in response to the difference therebetween a drive signal for said servomotor in order to automatically open the door as the traffic approaches the

door and to automatically close the door after the traffic has passed through the door.

5. The apparatus defined by claim 4 wherein the feedback means is so constructed and arranged that the drive signal supplied to move the door in either direction is non-linear and has a high initial level for a predetermined period to overcome door inertia and at the end of said period decreases to a substantially constant intermediate level which diminishes to zero.

6. The apparatus defined by claim 4 wherein the servomotor includes a control winding actuated by said drive signal and a damping winding, and wherein means are provided for automatically energizing said damping winding when the door reaches a predetermined point intermediate its open and closed positions and during the return of the door towards its closed position in order to develop a force for slowing down the door.

7. An operator for moving a door between open and closed positions, said operator comprising a servomechanism for moving said door between said positions, electrical circuit means providing a first electrical signal representing the closed position of the door in the absence of traffic adjacent the door and operated in response to movement of traffic adjacent the door to develop a second electrical signal representing the open position of the door, feedback means operated simultaneously with the movement of said door for developing a third electrical signal which varies during the movement of the door between a level equal to that of the first signal and a level equal to that of the second signal, and means for comparing said second and third signals during opening of the door to produce in response to the difference therebetween a control signal for driving said servomechanism in a direction to open said door until said door reaches said open position, the last named means being automatically operated by the difference between the first and third signals when said traffic has passed to drive said servomechanism in a direction to return the door to closed position.

8. An automatic operator for a door, said operator comprising a single servomotor operably connected to said door for moving it between open and closed position, a self balancing, variable voltage network for supplying drive voltage for said servomotor, said drive voltage being developed between a movable follower device in said network and a voltage reference, said network being balanced when the driving voltage is zero, electrical circuit means automatically operated in response to traffic approaching the door for unbalancing the network by changing the voltage reference from a first level representing the closed position of the door to a second level representing the open position of the door, thereby supplying a driving voltage causing said servomotor to open the door, feedback means connected to the servomotor and to said follower device for moving the latter in a direction to rebalance the network when the door reaches its open position, said circuit means being effective to again unbalance the network after the traffic has passed through the door by changing said reference from said second level back to said first level, thereby supplying a driving voltage causing the servomotor to close the door, the feedback means being effective during closing of the door to move the follower in a direction to rebalance the network.

9. The apparatus defined by claim 8 wherein the feedback means is constructed and arranged to move the follower device in such manner that the driving voltage for the servomotor during both the opening and closing of the door has a high initial value for overcoming door inertia, and a substantially constant intermediate value which diminishes to zero.

10. The apparatus defined by claim 8 wherein the servomotor includes a control winding energized by said drive voltage and a damping winding which, when energized, develops a field acting to slow down the motor, and wherein means are provided for energizing said damp-

ing winding at a predetermined position of the door in its return towards closed position.

11. The apparatus defined by claim 8 wherein the door may be opened manually in a direction opposite to the normal opening movement and without operating said circuit means in order to permit reverse movement of traffic through the door, the feedback means being so constructed and arranged that it is effective during such manual operation to drive said follower device in a direction to unbalance the network in order to develop a drive voltage which is effective to return the door to closed position when the door is released.

12. The apparatus defined by claim 8 wherein the feedback means includes a cam for moving said follower device, said cam including a first guide portion, a second guide portion and an intermediate guide portion disposed between the first and second portions, together with a first section interconnecting the first portion and the intermediate portion and a second section interconnecting the second portion and the intermediate portion, said follower device being disposed within the first section when the door is in closed position and being movable through the first section through the intermediate portion and into engagement with the second section when the door is opened automatically, said follower device moving from the second section back through the intermediate portion and back to the first section when the door is closed automatically, manual opening of said door from closed position in a direction opposite to the automatic opening being effective to move said follower device from the first section to the first portion in order to unbalance said network and develop a drive voltage for returning the door to closed position when the door is released.

13. An automatic operator for a door, said operator comprising means including a motor for automatically opening and closing the door in response to movement of traffic from a first side of the door to a second side, and means for storing a drive signal in the event that said door is manually opened from said second side to permit reverse movement of traffic from the second side of the door to the first side, and means automatically operated after the manually applied force has been released and after the reverse traffic has passed through the door to supply the stored signal to said motor to drive the latter in a direction to close the door.

14. In an automatic door operator, means including a motor for opening and closing the door, means for controlling said motor to effect the automatic opening and closing of the door in response to movement of traffic through the door, the last named means being constructed and arranged to permit manual opening of the door, and control means for developing a drive signal when said door is opened manually and for supplying said signal to said motor to automatically close the door when the manual opening force is removed and when the traffic has passed through the door.

15. In a door operator, means including a motor for driving the door, control means for controlling said motor to effect the automatic opening and closing of the door in response to movement of traffic through the door, means including a manually operable switch for selectively rendering the operator effective as a door closer by rendering the control means ineffective to open the door so that the door must be opened manually, and means for developing a drive signal when said door is opened manually and for supplying said signal to said motor to automatically close the door when the manual opening force is removed.

16. In an automatic door operator, means including a motor for driving the door, control means for controlling said motor to effect the automatic movement of the door between open and closed positions in response to movement of traffic through the door, and means for developing a drive signal in the event that said door is moved from one of said positions independently of the control means

and for supplying said drive signal to drive said motor in a direction to return the door to said one position.

17. An electric operator for a door supported for swinging movement on both sides of a doorway by manually pushing the door from its closed position, said operator being conditioned to function as a double-acting door closer for automatically returning the door to closed position from either side of the doorway when the door is released, said operator comprising a servomotor, a self balancing network for producing a driving voltage for said servomotor, said network being normally balanced when the door is closed so that no driving voltage is supplied to the servomotor, and means for unbalancing said network in response to manual opening of the door to produce a unidirectional driving voltage having a first polarity when the door is opened on a first side of the doorway and having an opposite polarity when the door is opened on a second side of the doorway, said driving voltage of first polarity being effective to drive said servomotor in a direction to return the door to closed position from said one side of the doorway when the door is released and said driving voltage of opposite polarity being effective to return the door to closed position from the second side of the doorway when the door is released.

18. An electric operator for a door supported for swinging movement on both sides of a doorway by manually pushing the door from its closed position, said operator being conditioned to function as a double-acting door closer for automatically returning the door to closed position from either side of the doorway when the door is released, said operator comprising a servomotor, a self balancing network for producing a driving voltage for said servomotor, said network being normally balanced when the door is closed so that no driving voltage is supplied to the servomotor, and means for unbalancing said network in response to manual opening of the door to produce a driving voltage for automatically returning the door to closed position from either side of the doorway when the door is released.

19. An electric operator for a door supported for swinging movement on both sides of a doorway by manually pushing the door from its closed position, said operator being conditioned to function as a double-acting door closer for automatically returning the door to closed position from either side of the doorway when the door is released, said operator comprising a servomotor, a self balancing network for producing a driving voltage for said servomotor, said network being normally balanced when the door is closed so that no driving voltage is supplied to the servomotor, and a follower device operably connected to the door and to said network for unbalancing said network in response to manual opening of the door to produce a unidirectional driving voltage having a first polarity when the door is opened on a first side of the doorway and having an opposite polarity when the door is opened on a second side of the doorway, said driving voltage of first polarity being effective to drive said servomotor in a direction to return the door to closed position from said one side of the doorway when the door is released and said driving voltage of opposite polarity being effective to return the door to closed position from the second side of the doorway when the door is released.

20. An electric operator for a door supported for swinging movement on both sides of a doorway by manually pushing the door from its closed position, said operator being conditioned to function as a double-acting door closer for automatically returning the door to closed position from either side of the doorway when the door is released, said operator comprising a servomotor, a self balancing network for producing a driving voltage for said servomotor, said network being normally balanced when the door is closed so that no driving voltage is supplied to the servomotor, and a follower device operably connected to the door and to the network for unbalancing said network in response to manual opening of the

door to produce a driving voltage for automatically returning the door to closed position from either side of the doorway when the door is released.

21. An automatic operator for a door comprising power means including an electric motor for moving the door between open and closed positions, control means operated in response to movement of traffic through the door for automatically energizing the power means to open the door in response to the approach of traffic and to close the door after the traffic has passed, means actuated by the application to said door of a force sufficient to move it in either direction from its closed position independently of the control means and in the absence of traffic for developing a drive voltage, and means for supplying the drive voltage to the motor so that the latter drives the door in a direction against said force, thereby inhibiting movement of said door from the closed position by wind and other similar forces.

22. An automatic operator for a door comprising power means including an electric motor for moving the door between open and closed positions, control means operated in response to movement of traffic through the door for automatically energizing the power means to open the door in response to the approach of traffic and to close the door after the traffic has passed, and means actuated by the application to said door of a force sufficient to open it from its closed position independently of the control means and in the absence of approaching traffic for supplying to said motor a drive voltage for actuating the motor to move the door in a direction tending to restore the door to closed position against said force, thereby inhibiting opening of said door by wind and other similar forces.

23. The apparatus defined by claim 22 wherein the voltage supplying means is constructed and arranged to develop a drive voltage which increases in proportion to the displacement of the door within a predetermined angle of the closed position.

24. The apparatus defined by claim 22 wherein the door is mounted for swinging movement upon a door frame and wherein the voltage supplying means develop a drive voltage of maximum amplitude before the door has been moved beyond the frame by the applied force.

25. An operator for a door, said operator comprising means including an electric motor drivingly connected to said door to move the latter between open and closed positions, an electrically controlled damping means for damping the door during a predetermined portion of its movement near one of said positions, means for developing a driving voltage for the motor to move the door towards said one position at relatively high speed until the door reaches the said predetermined portion of its movement, and a control circuit including means operable when the door reaches said predetermined portion of its movement for removing said driving voltage from said motor and for energizing said damping means, thereby quickly slowing down the moving door and then moving the door toward said one position at slower speed.

26. An operator for a door, said operator comprising means including a servomotor drivingly connected to said door to move the latter between open and closed positions, said motor having a control winding for driving the motor and a damping winding which, when energized, develops a field for slowing down the motor, means for developing a driving voltage for the control winding to move the door towards its closed position at relatively high speed until the door reaches a predetermined portion of its movement near the closed position, and a control circuit including means operable when the door reaches said predetermined portion of its movement for removing said driving voltage from said motor during a predetermined time interval and for energizing said damping winding, thereby quickly slow-

ing down the moving door and then moving the door toward the closed position at slower speed.

27. An operator for a door, said operator comprising means including a servomotor drivingly connected to said door to move the latter between open and closed positions, said motor having a control winding for driving the motor and a damping winding which, when energized, develops a field for slowing down the motor, and a control circuit operated by movement of traffic through the door for supplying driving voltage to the control winding to open the door when traffic approaches and to close the door when the traffic passes, said circuit including means operable when the door reaches a predetermined portion of its movement near the closed position of the door for energizing said damping winding to move the door toward said closed position at slow speed, the last named means being effective to maintain the damping winding energized in the absence of traffic through the door in order to provide a force tending to prevent movement of the door from its closed position.

28. An operator for a door, said operator comprising means including an electric motor drivingly connected to said door to move the latter between open and closed positions, an electrically controlled damping means for damping the door during a predetermined portion of its movement near one of said positions, means for developing a driving voltage for the motor to move the door towards said one position at relatively high speed until the door reaches the said predetermined portion of its movement, and a control circuit including a time delay subcircuit operable when the door reaches said predetermined portion of its movement for removing said driving voltage from said motor for a predetermined interval and for energizing said damping means, thereby quickly slowing down the moving door and then moving the door toward said one position at slower speed, said subcircuit including a source of D.C. power, a relay, a rectifier circuit connected across the relay, a condenser in said subcircuit, and a door position sensitive switch actuated when said door reaches said predetermined portion of its movement to charge said condenser from said source through said relay, thereby energizing said relay during said predetermined interval, said rectifier circuit being connected to provide a high resistance to the condenser charging current, said relay having contacts effective when the relay is energized to remove the driving voltage from the motor and to energize the damping means, said relay being deenergized by the decrease in condenser charging current, said door switch being effective during opening of said door to provide a discharge path for the condenser through the rectifier circuit, thereby to reset the subcircuit for the next door closing operation.

29. An operator for a door comprising means including a motor for automatically moving the door between open and closed positions in response to movement of traffic through the door, said motor including a damping winding for inhibiting movement of said door from its closed position by developing a resistive force proportional to the rate of any displacement of the door from the closed position, and control means for said motor means and said damping winding, said control means being effective to energize said damping winding while said door is in the closed position to provide a resistive force to oppose sudden door displacements.

30. An automatic operator for a door, said operator comprising means including an electric motor operably connected to the door to move it between open and closed positions, damping means for slowing down the door when it reaches a predetermined point in its travel towards the closed position, a control circuit responsive to movement of traffic through the door for rendering the damping means ineffective and for supplying a driving voltage to said motor to move the door automatically

between said positions, and means operated when the door reaches said predetermined point and for a predetermined interval thereafter for operating said damping means independently of said control circuit so that the movement of traffic during said predetermined interval does not render the damping means ineffective, thereby avoiding return of the door to closed position at high speed.

31. An automatic operator for a door, said operator comprising means including a servomotor operably connected to the door to move it between open and closed positions, said motor having a control winding for driving the motor and a damping winding which, when energized, slows down the door, a control circuit responsive to movement of traffic through the door for rendering the damping winding ineffective and for supplying a driving voltage to said control winding to move the door automatically between said positions, and means operated when said door reaches a predetermined point in its travel towards closed position and for a predetermined interval thereafter for energizing said damping winding independently of said control circuit so that the movement of traffic during said predetermined interval does not render the damping winding ineffective, thereby avoiding return of the door to closed position at high speed.

32. An automatic operator for a door, said operator comprising means including an electric motor operably connected to the door to move it between open and closed positions, damping means for slowing down the door when it reaches a predetermined point in its travel toward the closed position, a control circuit responsive to movement of traffic through the door for rendering the damping means ineffective and for supplying a driving voltage to said motor to move the door automatically between said positions, and means operated when said door reaches said predetermined point and for a predetermined interval thereafter for removing the driving voltage from said motor and for operating said damping means independently of said control circuit so that the movement of traffic during said predetermined interval does not render the damping means ineffective, thereby to slow down the door quickly during the predetermined interval and to avoid return of the door to closed position at high speed.

33. An automatic operator for a door, said operator comprising means including a servomotor operably connected to the door to move it between open and closed positions, said motor having a control winding for driving the motor and a damping winding which, when energized, slows down the door and provides a force tending to hold the door in its closed position, a control circuit responsive to movement of traffic through the door for rendering the damping winding ineffective to hold the door in closed position and for supplying a driving voltage to said motor to automatically open the door when the traffic approaches and to return the door to closed position after the traffic has passed, and means operated when said door reaches a predetermined point in its return to closed position and for a predetermined interval thereafter for removing the driving voltage from the control winding and for energizing said damping winding independently of said control circuit so that the movement of traffic during said predetermined interval does not render the damping winding ineffective, thereby to slow down the door quickly during said predetermined interval and to avoid return of the door to closed position at high speed.

34. An electric operator for a door, said operator comprising an electric motor for moving said door between open and closed positions, an electrically controlled damping means adapted to be connected to a power source and effective to provide a force tending to hold the door in closed position, an electrical control circuit including a first subcircuit actuated by approach of traffic to the door for supplying a drive signal to the motor to open the door and for disconnecting the damping means from

the source, said first subcircuit being effective when the traffic moves through and past the door to provide a drive voltage for the motor to return the door towards closed position, said circuit including a door position sensitive switch actuated when said door moves to a predetermined point in its travel towards its closed positions to complete a circuit for connecting said damping means to said source and to interrupt the drive to said motor, switch means controlled by said door switch and operable for a predetermined time interval following actuation of said door switch for completing a second subcircuit for energizing said damping means independently of said first subcircuit and also of said door switch during said predetermined time interval, said switch means assuring that said damping means is energized during said predetermined time interval irrespective of approach of traffic, thereby preventing said first subcircuit from disconnecting the damping means from the source during said interval and, hence, preventing return of the door at high speed to its closed position.

35. An electric operator for a door, said operator comprising a servomotor for moving said door between open and closed positions, said motor including a control winding for driving the motor and a damping winding adapted to be connected to a power source and effective to provide a force tending to hold the door in closed position, an electrical control circuit including a first subcircuit actuated by approach of traffic to the door supplying a drive signal to the control winding to open the door and for disconnecting the damping winding from the source to release said force, said first subcircuit being effective when the traffic moves through and past the door to provide a drive voltage for the control winding to return the door towards closed position, said circuit including a door position sensitive switch actuated when said door moves to a predetermined point in its travel towards its closed positions to complete a circuit for connecting said damping winding to said source and to interrupt the drive to said control winding, switch means controlled by said door switch and operable for a predetermined time interval following actuation of said door switch for completing a second subcircuit for energizing said damping winding independently of said first subcircuit and also of said door switch during said predetermined time interval, said switch means assuring that said damping winding is energized during said predetermined time interval irrespective of approach of traffic, thereby preventing said first subcircuit from disconnecting the damping winding from the source during said interval and, hence, preventing return of the door at high speed to its closed position.

36. An automatic operator for a door comprising power means including an electric motor for moving the door between open and closed positions, control means operated in response to movement of traffic through the door for automatically energizing the power means to open the door in response to the approach of traffic and to close the door after the traffic has passed, and means actuated by the application to said door of a force sufficient to move it independently of the control means and in the absence of traffic for supplying to said motor a drive voltage for actuating the motor to move the door in a direction against said force, thereby inhibiting movement of said door by wind and other similar forces, the last named means being constructed and arranged to develop a drive voltage which increases proportionately to the displacement of the door by the applied force.

37. In an automatic door operator for moving a door between open and closed positions to permit the passage of traffic from an entrance side of the door to an exit side, the combination of a drive mechanism including an electric motor and operably connected to the door, means responsive to movement of traffic adjacent the entrance side of the door for rendering the drive mechanism effective to move the door from its closed position to its open

position, means automatically operative after traffic has passed through the door and beyond the exit side thereof for rendering the drive mechanism effective to return the door from the open position to the closed position, and means automatically operated by inadvertent movement of traffic to a position within a predetermined distance of the exit side of the door while the door is moving from one of said positions to the other for rendering the motor ineffective to drive the door and, at the same time, for holding the door in an intermediate position between the open and closed positions until the last named traffic has again moved beyond the predetermined distance from the exit side of the door.

38. In an automatic door operator for moving a door between open and closed positions to permit the passage of traffic from an entrance side of the door to an exit side, the combination of a drive mechanism including a servomotor and operably connected to the door, means responsive to movement of traffic adjacent the entrance side of the door for rendering the drive mechanism effective to move the door from its closed position to its open position, means automatically operative after traffic has passed through the door and beyond the exit side thereof for rendering the drive mechanism effective to return the door from the open position to the closed position, said servomotor having a damping winding therein for developing a field tending to prevent movement of the door, means for preventing energization of said servomotor to open said door unless the exit side of the door is clear of traffic, and means automatically operated by inadvertent movement of traffic to a position within a predetermined distance of the exit side of the door while the door is returning to closed position for rendering the motor ineffective to drive the door and, at the same time, energizing the damping winding in order to hold the door in an intermediate position between the open and closed positions until the last named traffic has again moved beyond the predetermined distance from the exit side of the door.

39. In an automatic door operator for moving a door between open and closed positions to permit the passage of traffic from an entrance side of the door to an exit side, the combination of a drive mechanism including a servomotor and operably connected to the door, means including an entrance treadle mat adjacent the entrance side of the door for rendering the drive mechanism effective to move the door from its closed position to its open position in response to movement of traffic onto the entrance mat, means including an exit treadle mat located adjacent the exit side of the door for rendering the drive mechanism automatically effective to return the door from the open position to the closed position as soon as the traffic has passed through the door and off of the exit treadle mat, said servomotor having a damping winding therein for developing a field tending to prevent movement of the door, means for preventing energization of said motor to open said door in response to movement of traffic onto the entrance mat if traffic is at that time located on the exit mat, and means automatically operated by inadvertent movement of traffic onto the exit mat while the door is returning to closed position for rendering the servomotor ineffective to drive the door and for energizing the damping winding to hold the door in an intermediate position between the open and closed positions until the last named traffic has again moved off of the exit mat.

40. In an automatic door operator for moving a door between open and closed positions to permit the passage of traffic from an entrance side of the door to an exit side, the combination of a drive mechanism operably connected to the door, means including an entrance treadle mat adjacent the entrance side of the door for rendering the drive mechanism effective to move the door from its closed position to its open position in response to movement of traffic onto the entrance mat, means including an exit treadle mat located adjacent the exit side of the door for rendering the drive mechanism automatically ef-

fective to return the door from the open position to the closed position as soon as the traffic has passed through the door and off of the exit treadle mat, and means automatically operated by inadvertent movement of traffic onto the exit treadle mat while the door is returning to closed position for holding the door in an intermediate position between the open and closed positions until the last named traffic has again moved off of the exit mat.

41. In an automatic door operator for moving a door between open and closed positions to permit the passage of traffic from an entrance side of the door to an exit side, the combination of a drive mechanism including a motor and operably connected to the door, means including an entrance treadle mat adjacent the entrance side of the door for rendering the drive mechanism effective to move the door from its closed position to its open position in response to movement of traffic onto the entrance mat, means including an exit treadle mat located adjacent the exit side of the door for rendering the drive mechanism automatically effective to return the door from the open position to the closed position as soon as the traffic has passed through the door and off of the exit treadle mat, and means automatically operated by inadvertent movement of traffic onto the exit mat while the door is moving from one of said positions to the other for rendering the motor ineffective to move the door and, at the same time, for holding the door in an intermediate position between the open and closed positions until the last named traffic has again moved off of the exit mat.

42. In an operator for moving a door having an entrance side and an exit side, the combination of means for automatically moving the door from a closed position to an open position in response to the movement of traffic adjacent the entrance side of the door and for then returning the door from its open position to its closed position in response to movement of traffic beyond the exit side of the door, and means for resisting movement of the door from its closed position in response to an externally applied force and in the absence of traffic, the last named means being so constructed and arranged that the resistance offered is proportional to the rate of any displacement of the door from the closed position by the externally applied force and, hence, is effective against sudden door displacements caused by such factors as wind gusts.

43. In an operator for moving a door having an entrance side and an exit side, the combination of means including a motor for automatically moving the door from a closed position to an open position in response to the movement of traffic adjacent the entrance side of the door

and for then returning the door from its open position to its closed position in response to movement of traffic beyond the exit side of the door, and means for rendering the motor effective to resist movement of the door from its closed position in response to any externally applied force in the absence of traffic, the last named means being so constructed and arranged that the resistance offered is proportional to the rate of any displacement of the door from the closed position by the externally applied force and, hence, is effective against sudden door displacements caused by such factors as wind gusts.

44. The apparatus defined by claim 2 wherein the servomotor includes a control winding actuated by said control signal and damping means rendered automatically effective to slow down the door when the door reaches a predetermined point in its movement towards but in advance of the open position.

45. The apparatus defined by claim 37 wherein said drive mechanism includes an electrically operated braking means and wherein said door is held in said intermediate position by actuating said braking means.

46. The apparatus defined by claim 37 wherein the means for holding the door in an intermediate position is effective only if traffic moves within a predetermined distance of the exit side of the door while the door is returning from the open position to the closed position.

47. The apparatus defined by claim 45 wherein the means for holding the door in an intermediate position is effective only if traffic moves within a predetermined distance of the exit side of the door while the door is returning from the open position to the closed position.

48. The apparatus defined by claim 41 wherein said drive mechanism includes an electrically operated braking means and wherein said door is held in said intermediate position by actuating said braking means.

49. The apparatus defined by claim 48 wherein the means for holding the door in an intermediate position is effective only if traffic moves onto the exit mat while the door is returning from the open position to the closed position.
